WIRE-FILLER-SECURING MEANS FOR GATE-FRAMES.

1,259,151.

Specification of Letters Patent. Patented Mar. 12, 1918.

Application filed January 17, 1916. Serial No. 72,619.

To all whom it may concern:

Be it known that I, WILLIAM H. SOMMER, a citizen of the United States, residing at Peoria, in the county of Peoria and State of Illinois, have invented new and useful Improvements in Wire-Filler-Securing Means for Gate-Frames, of which the following is a specification.

This invention has reference to wire filler 10 securing means for gate frames.

One of the objects of the present invention is to provide a machine for connecting the cross wires forming the filler of a gate frame, where they intersect, after the cross 15 wires have been secured to the frame; the connecting means, in this instance, comprising preferably a tie-wire which crosses the filler wires where they intersect, the opposite ends of the tie wires being suitably bent 20 about one or the other or both of the cross wires to secure them together.

The invention has for a further object to provide a machine for supporting the gate frame with the cross wires having been previously secured thereto, and for moving said frame in a step-by-step movement for progressively bringing the successive rows of intersections of the filler wires simultaneously in the path of the mechanisms which 25 are employed for severing, forming, and securing the tie-wires about the intersections of said filler wires.

A further object of the invention is to provide a machine for connecting the intersections 30 of the cross or filler wires of a gate frame, said machine being adapted to receive a gate frame in which the cross or filler wires have been previously secured, the feeding means for the frame including movable 35 members timed in their relation to the wire connecting means, so that a row of intersections of the cross or filler wires may be brought into the path of the wire connecting means at suitable intervals, and then stopped 40 during the operation of the mechanisms employed for connecting the intersections of the cross or filler wires, by a suitable tie-wire or lock; these operations being carried on intermittently and progressively until each 45 of the succeeding rows of cross or tie-wire intersections have been operated upon by the connecting mechanisms, at which time the completed frame is removed from the machine, means being provided for reversing 50

the operation of the frame carrying elements 55 whereby they may be moved to their normal or receiving positions for another frame; the wire connecting means including tie-wire stock feeding mechanism, devices for severing tie-wires from the stock, devices for 60 forming the tie-wires into staple-like members, and devices for projecting said staple-like members across the intersections of the cross or filler wires, and locking said staple-like members about the intersections of said 65 cross or filler wires. All of the movable parts of the wire connecting mechanism are located on the machine above the path of travel of the gate through the machine.

A further object of the invention, is to 70 provide in a machine of the character referred to, a carrier or movable support for moving the gate through the machine, said carrier or movable support adapted to be actuated in a step-by-step movement; means 75 for moving the carrier to preliminarily advance the gate to a position with a row of intersections of the wires in the frame immediately in the rear of the wire connecting mechanism, from which point the carrier 80 with the gate is advanced in a step-by-step movement through the machine by other means.

A further object of the invention, is to provide in a machine of the character referred to, wire connecting means, feeding means for the gate, said feeding means being movable in a step-by-step movement for advancing the gate through the machine, and reversible to receiving position for another 85 frame, and positng means for the frame, said last-mentioned means movable at predetermined intervals and just prior to the 90 operation of the wire connecting means, for positioning the wires to be connected.

In the manufacture of wire gates, that is, a gate comprising a frame with cross or filler wires secured thereto, it has been the practice to make a suitable frame and cut from a piece of previously woven fence-fabric, composed preferably of longitudinal strand or line wires and transverse stay or picket wires, united in a suitable manner, a section of said fabric of sufficient length to 100 form the filler for the frame; and this filler has been laid upon the frame and the ends of the longitudinal strand or line wires have been secured to opposite end bars of the gate 105

frame. In some instances the securing of the ends of the longitudinal strand or line wires has been done by hand, by first securing one end of each of said longitudinal strand or line wires to one of the vertical end bars of the gate frame, preferably by wrapping the same therearound, and securing the opposite ends of each of said wires to the opposite end bars of the frame in the same manner. In some instances this securing operation of the ends of the longitudinal strand or line wires to the opposite end bars of the gate frame, has been done by a machine specially designed for this purpose, but in each instance, whether the securing of the longitudinal strand or line wires has been done by hand, or by machine, there has been no staying or securing means for the stays or picket wires to the top and bottom bars of the frame, unless such staying has been accomplished by securing small sections of wires to the top and bottom marginal wires of the section of fabric and also to the top and bottom bars of the frame. Even in cases of this kind, with the ends of the longitudinal strand or line wires secured to the opposite end bars of the frame, by being wrapped thereabout, and by the use of short interposed stays between the top marginal wire and the top bar of the frame, and the lower marginal wire and bottom bar of the frame, the fabric is not secured as taut as it should be in the frame and it soon becomes loose through the action of the elements or pressure against the fabric, causing the wrappings of the ends of the longitudinal strand or line wires on the end bars of the frame to become loose and slip on the frame, instead of remaining as a permanent and fixed part of the frame and serving as a reinforcement for said frame.

By my invention I do away with the use of sections of a fabric, and secure to the frame longitudinal strand or line wires and vertical stays or picket wires, the former having their ends secured in a suitable manner to the opposite end bars of the frame, and the latter having their ends secured in a suitable manner to the top and bottom bars of the frame, the intersections of said wires being connected by a tie-wire or similar member, which not only unites the intersections of said cross or filler wires, but makes the filler taut within the frame, forming a union therewith and not only serving as a filler therefor, but also reinforcing said frame. I prefer that the ends of the longitudinal strand or line wires and the stays or picket wires should be passed through the opposite end bars, and top and bottom bars of the frame, and the outer ends of such wires headed. The manner of securing the ends of the filler wires to the frame, by heading, does not form a part of the present machine, but is accomplished in a machine,

which is a separate invention and forms the subject matter of another application for patent.

That the invention may be more fully understood, reference is had to the accompanying drawings, in which:—

Figures 1 and 2, together, show a complete front elevation of my machine for securing the wire filler of a gate frame, parts being broken away and in section to show certain details of construction, also showing a gate frame and the mechanisms in the position they would assume when the wire connecting mechanism is operated on the filler wires;

Fig. 3 is a side elevation of the right-hand side of the machine, as the same would appear looking at the right-hand side of Fig. 2, the position of the parts being the same;

Fig. 4 is a side elevation of the left-hand side of the machine, as the same would appear looking at the left-hand side of Fig. 1, the position of the parts being the same;

Fig. 5 is a vertical cross section as the same would appear if taken on the line 5—5 of Fig. 1, the position of the parts being the same;

Fig. 6 is a vertical cross section as the same would appear if taken on the line 6—6 of Fig. 2, the position of the parts being the same;

Fig. 7 is a vertical cross section in elevation as the same would appear if taken on the line 7—7 of Fig. 8, this view illustrating the guiding and positing means for the gate frame and wires, and the actuating means therefor, the parts being in an elevated position;

Fig. 8 is a front elevation of the mechanism shown in Fig. 7;

Fig. 9 is a detail in plan showing a friction clamp and guiding means for the gate frame, which is also a part of the positing mechanism;

Fig. 10 is a side elevation of the parts shown in Fig. 9;

Fig. 11 is a detailed view of one of the wire guiding and positing fingers;

Fig. 12 is a front elevation in section showing the staple tie-wire feeding mechanism and operating means therefor;

Fig. 13 is a plan view as the same would appear if taken on the line 13—13 of Figs. 1 and 2;

Fig. 14 is a plan view of the guiding and positing means for the gate frame, as the same would appear if taken on the line 14—14 of Fig. 7;

Fig. 15 is a detail side elevation, partly in section, of the clutch controlling means on the driving shaft;

Fig. 16 is a detail elevation, partly in section, of the mechanism shown in Fig. 15, looking at the left-hand side of Fig. 15;

Fig. 17 is a detail of the clutch and connections on the gate frame feeding shaft used for returning the gate feeding means to its initial or receiving position;

5 Fig. 18 is a sectional detail in elevation as the same would appear if taken on the line 18—18 of Fig. 13, looking in the direction of the arrow on said figure, the parts illustrated, being those connected with the gate frame feeding shaft, for moving the gate feeding means forward;

10 Fig. 19 is a longitudinal sectional detail of the stay tie-wire feeding means shown in Figs. 2 and 3;

15 Fig. 20 is a transverse sectional detail of Fig. 19;

20 Fig. 21 is a detail front elevation of one set of mechanisms for severing a tie-wire from the tie-wire stock, forming the tie-wire into a staple-like member, and projecting the staple-like member and locking the same about intersecting wires, the parts being in an upward or inoperative position;

25 Fig. 22 is a vertical sectional view through the operative parts of the mechanisms shown in Fig. 21;

30 Fig. 23 is a sectional detail somewhat similar to Fig. 22 with the exception that the tie-wire stock has been fed across the face of the cutter a sufficient distance for the severance of a section of the tie-wire from said stock, the tie-wire portion of the stock extending across the anvil, the parts being in a position just prior to the severance of 35 the tie-wire from the tie-wire stock;

35 Fig. 24 is a view similar to Fig. 23 with the exception that a section of the tie-wire has been severed from the tie-wire stock and the staple-like member formed from the tie-wire over the anvil, the parts being in a 40 position just prior to the punch moving the anvil and projecting the staple-like member across the juncture of the wires to be secured;

45 Fig. 25 is a view similar to Figs. 23 and 24, with the exception that the upper die member or movable block has been moved to engaging position with a lower die member for the purpose of holding the cross wires 50 between the same, and the punch having passed the anvil forces the staple-like member across the juncture of the wires and clenches the ends of the staple-like member around the juncture of the wires, by engagement with the lower die member;

55 Fig. 26 is a sectional detail in plan as the same would appear if taken on the line 26—26 of Fig. 23;

60 Fig. 27 is a sectional detail in plan as the same would appear if taken on the line 27—27 of Fig. 24;

65 Fig. 28 is a sectional detail in plan as the same would appear if taken on line 28—28 of Fig. 25;

65 Fig. 29 shows a finished gate, the wire

filler being connected by a means such as disclosed in my machine, the gate containing fewer longitudinal strand or line wires than in the wire filler shown in the frame in Fig. 13;

70 Figs. 30, 31 and 32 show different views of the tie-wire for connecting the intersections of the cross wires;

75 Fig. 33 is a detailed side elevation of the friction clamp and guiding means shown in Figs. 9 and 10 and the manner of supporting the same on its vertically movable cross bar forming a part of the positng mechanism;

80 Fig. 34 is a detailed side elevation of a guiding roller for the gate frame and the manner of supporting the same upon the movable cross bars forming a part of the positng mechanism, and

85 Fig. 35 is a partial front elevation of that portion of the machine shown in Fig. 2, illustrating a means adapted to be connected with power for automatically advancing the gate to operative position in the machine.

90 The main or supporting frame parts of the machine, comprise the right- and left-hand end castings or frames 33 and 34, said end castings or frames being spaced a suitable distance from each other and connected by means of the upper and lower channel-shaped cross frames 35 and 36, which may be integral with the end castings or frames 33 and 34, or separate castings or frames suitably connected thereto. Extending cross-

95 wise of the machine and suitably secured to the lower front and bottom portion of the upper cross frame 35, is an angular bar 37, and said bar, as will be further explained, has connected thereto the delivery end of a plurality of tie-wire stock guiding tubes 38.

100 The front vertical face of said cross frame 35 serves as a bed plate, on which is operatively mounted cutting mechanism for severing sections from each of the wires forming the tie-wire stock, anvils over which the severed sections of the tie-wire stock are

105 formed into staple-like tie-wire members, and punches or tools for driving the staple-like members across the intersections of the cross wires in the gate frame which are to be secured; the anvils preferably being pivotedly connected with a stationary cross-bar 39, the opposite ends of which are secured to the cross frame 35, and the rear face of said cross-bar 39 being spaced from

110 the front face of the cross frame 35 to allow for the up and down movement of the parts included in the mechanism for severing, forming and driving the staple-like members. The front vertical face of the lower

115 cross frame 36 serves as a bed plate on which is mounted the lower die members which are included in the wire-connecting mechanism, to be hereinafter more specifically described;

120 also the guiding means for certain of the 125

130

- wires in the gate frame, preferably those wires known as the line or longitudinal wires in the frame. On said lower cross frame 36 is also mounted, as will be further explained, the guiding and positing means included in the mechanism for moving the gate frame to properly position the cross wires thereof, just prior to the operation of the wire connecting mechanisms.
- 10 Extending crosswise of the machine is a driving shaft 40, said shaft journaled in suitable bearings or boxings 41 removably secured on the upper cross frame 35. This driving shaft 40 receives its power through 15 a driving pulley 42, loosely carried on one end of said shaft and adapted to be belted to a line shaft or some other suitable source of power. Clutch mechanism is provided, to be described, for connecting the driving 20 pulley 42 with the driving shaft 40; whereby power may be transmitted from the driving shaft 40 to the operative parts or mechanisms of the machine. On the end of the driving shaft 40, opposite to that on which 25 is carried the driving pulley 42, there is secured a small driving gear or pinion 43, which meshes with and drives the larger gear wheel 44, carried on one end of a timing shaft 45, said shaft being located in advance 30 of and above the driving shaft 40, and the opposite ends of said timing shaft 45 are journaled in suitable boxings or bearings mounted on the cross frame 35. On the end of the timing shaft 45, opposite to that on which 35 which is located the large gear wheel 44, is secured a cam wheel 46, through and by means of which is operated the feeding mechanism for advancing the wires forming the tie-wire stock, a distance sufficient to 40 provide the sections of wire which produce the staple-like members. Carried on the timing shaft 45 are a series of eccentrics 47, and a series of eccentrics 48; the eccentrics 47, as will be more fully explained, being 45 operatively connected with the means for driving the punches or tools which advance the staple-like members across the intersections of the cross wires, and the eccentrics 48; as will be more fully explained, are operatively connected with the means employed for actuating the tie-wire stock severing means and a staple-like member forming means; also carried at a suitable point 50 on the timing shaft 45 is a cam wheel 49 through and by means of which are operated the parts controlling the movement of the guiding and positing means for the gate frame and wires connected thereto; also carried on the end of the timing shaft 45, adjacent 55 the large gear wheel 44, is an eccentric 50 which operates the parts employed for advancing the carrier or movable support on which is mounted the gate frame, for progressively and successively advancing the 60 rows of intersections of the cross wires in

the gate frame for the connection of the staple-like members thereto, to unite the same.

I have stated that the carrier or movable members for advancing the gate frame in the machine, is operated through and by means of the eccentric 50 carried on one end of the timing shaft 45. To return this carrier or movable support to a position for receiving another gate frame, the same is operated directly from the drive shaft 40, through and by means of a small pulley wheel 51 carried on the end of the driving shaft 40, adjacent to the driving pulley 42, a belt 52 being driven by said pulley wheel 51 and in turn operating a pulley wheel 53 loosely carried on one end of a shaft 54, included in the mechanism for advancing or reversing the movement of the gate carrier or movable support. This shaft 54 is journaled in suitable boxings or bearings 56 secured to the castings or frames 33 and 34. The pulley wheel 53 is adapted by means of certain clutch mechanism, to be described, to be thrown into or out of operative connection with said shaft 54. It will be understood that the pulley wheel 53 through and by means of the belt 52, driven by the pulley wheel 51, is in operation all of the time that the pulley wheel 42 is in operation and that the pulley wheel 53 will rotate in the same direction as the driving pulley 42 rotates; such rotation when the pulley wheel 53 is clutch connected with the shaft 54, will reverse the direction of movement of the gate frame carrier or movable support to return the same to its initial or receiving position, and by means of the gearing between the driving shaft 40 and the timing shaft 45, said shaft 45 through its connections with the shaft 54, to be described, will operate said shaft in a direction to advance a gate to present the rows of intersections of the cross wires therein to the wire connecting mechanisms.

Secured to the shaft 54 which serves as the shaft through which power is imparted to the carrier or movable support for advancing a gate in the machine, or for reversing the carrier or movable support to a position to receive another gate, is a toothed wheel 263. Loosely carried on said shaft 54 adjacent said toothed wheel 263, is a sleeve or collar 264, and attached to said sleeve or collar is an operator's lever 265, mounted upon which is a spring pressed detent or pawl 266, adapted to engage with the teeth of the wheel 263. Through and by means of the parts just described, the operator of the machine is enabled to rotate the shaft 54 in a step-by-step movement, forwardly, for the purpose of advancing the carrier or movable support, after a gate has been placed upon said carrier or movable support, to preliminarily advance the

gate to a position with a row of intersections of the wires in the gate frame immediately to the rear of the wire connecting mechanism, from which point the gate with 5 the rows of intersections of the wires is progressively and successfully moved through the machine, by means to be described.

I will now describe the clutch mechanism and the controlling means therefor, 10 through and by means of which the driving shaft 40 receives power from the driving pulley 42, enabling the driving shaft to transmit motion to the operative parts of the machine, reference being had to Figs. 2, 15 3, 15 and 16, respectively:—

The hub of the driving pulley 42 is formed with an extension having a clutch face 57, of suitable construction. This clutch part of the driving pulley 42 is adapted to be engaged by means of a clutch part 58 forming 20 part of a sleeve 59 having a spline and groove connection with the driving shaft 40, and said sleeve is formed with a grooved collar 60, the front face of said collar having a cam surface 61. 62 is a pin slidably arranged in a barrel or sleeve 63 forming a part of a bracket 64 secured to the casting or frame member 35. This pin 62 is adapted to enter between the clutch part 58 on 25 the sleeve 59 and the cam face 61 on the grooved collar 60 of said sleeve, bearing against the cam face of said collar, and when in said position, normally holds the clutch faces 57 and 58 in disengaged relation, in the manner shown in Fig. 16, in which position the driving shaft 40 will remain stationary, although the driving pulley 42 may be rotated through the application of power thereto, from a line shaft, or 30 some other suitable source of power. The pin 62 is provided with a notch or tooth 64^a adapted to be engaged by the end engaging portion 65 of a rod or stem 66, when the pin 62 has been lowered so that the 35 spring 67 (see Fig. 15) may force the rod or stem 66, causing its engaging end 65 to enter into the notch or tooth 64^a on the pin 62, holding the pin in lowered or disengaged relation with the cam face 61 on the sleeve 59, which will permit said sleeve, in a manner to be explained, to be moved endwise on the shaft 40 so as to cause the clutch faces 57 and 58 to enter into locking relation whereby rotation of the pulley wheel 42 will be correspondingly imparted to the driving shaft 40. The rod or stem 66 is 45 operatively carried in an angular, tubular extension 68 of the barrel or sleeve 63, the spring 67 bearing between the engaging end 50 portion 65 of said rod or stem 66 and the closed end of the angular, tubular extension 68. The pin 62 is connected with a coupling 69 having a bifurcated portion 70 which straddles and is secured to a bar 71, said bar 55 at one end having a pivotal connection at

72 with a frame part 73, and its opposite end having a pivotal connection at 74 with an upstanding bar 75, the lower end of which is pivotally connected at 76 to a foot lever 77, pivoted at 78 to the end casting 70 or frame 33, said foot lever having the foot-engaging portion 79. The rod or stem 66 is connected to a bar 80 which in turn has a pivotal connection at 81 with a hand lever 82, said hand lever being pivotally connected at 84 with the bars 71 and 75. The foot lever 77 is held in its normal raised position by means of a spring 83, one end connected with the lever 77, and the other end secured to the end casting or frame 33. 80 Engaging the grooved collar 60 of the sleeve 59 is a yoke 84, said yoke being connected to a rocking stem or rod 85 journaled in a bearing formed on the bracket 64. To the rocking stem or rod 85 is connected an arm 86, said arm 86, stem or rod 85, and the yoke 84, being retained in the normal inoperative position shown in Fig. 16 by 85 means of a spring 87, one end of the spring being connected with the outer end of the arm 86 and the opposite end of the spring being connected with one of the bearings or boxings for the driving shaft 40. The arm 86 just referred to has connected thereto, intermediate its length, a bar 88, and said 90 bar 88 is in turn connected to the bar 71.

Assuming that the parts just described are in their normal inoperative positions shown in Figs. 15 and 16, and that the operator is desirous of connecting the driving pulley 42 to the driving shaft 40, through the agency of the clutch parts 57 and 58, he will place his foot on the foot-engaging portion 79 of the lever 77, press said lever downwardly, moving the bar 75 100 also downwardly in the direction of its length, which movement will oscillate the bar 71, depressing the pin 62, releasing it from engagement with the cam face 61 of the collar 60 on the sleeve 59 until the notch 105 or tooth 64^a is brought opposite the engaging end 65 of the rod or stem 66, when the spring 67 will act, causing said engaging end portion 65 to be moved forwardly into engaging and locking relation with the 110 notch or tooth 64^a of said pin 62; at the same time that the pin 62 is released from the cam face 61 of said collar 60, the arm 86 through its connection with the bar 71 will be moved downwardly, rocking the 115 stem or rod 85, actuating the yoke 84 and moving the sleeve 59 on the driving shaft 40 so as to cause the clutch part 58 to engage and have a locking relation with the clutch part 57 on the driving pulley 42. 120 It is obvious when the parts have assumed this relation that power may be transmitted from the driving pulley 42 through the shaft 40 to the other operative parts of the machine. The operator, through and by 125

means of the hand lever 82, has full control of the operation of the machine and may disconnect the clutch engaging relation of the clutch parts 57 and 58, by moving the 5 lever 82 outwardly, which will disengage the engaging end portion 65 of the rod or stem 66 from the notch or tooth 64^a of the pin 62, allowing both springs 87 and 83 to act, the former raising the arm 86 which 10 will slide the sleeve 59 to a position on the shaft 40, permitting the spring 83 to lift the lever 77, and the bars 75 and 71, which will in turn raise the pin 62, and it, bearing against the cam face 61 of the collar 60, will 15 force it to hold it and the clutch part 58 in the disengaged position shown in Fig. 16; thus, to bring about a clutch engaging relation between the clutch parts 57 and 58 on the driving shaft 40, the operator need 20 only, by means of his foot, depress the lever 77, and to separate such clutch parts and hold them in inoperative and disengaged relation, the operator need only move the lever 82 toward him, allowing the springs 83 and 25 87 to act to return the parts to the position shown in Figs. 15 and 16.

The carrier or movable support for the gate frame, by means of which the frame is held in proper relation to the working parts 30 of the machine and also properly advanced through the machine in a step-by-step movement, and the guiding and positing means for positioning the rows of intersections of the wires in the gate frame, will 35 now be described, and in this connection a description will be first given of a gate frame and the wires therein, the intersections of which are to be connected by staple-like members:—

40 Referring to Figs. 29 to 32, both inclusive, a gate frame is shown, preferably made of tubing, the top bar *a* and the two end bars *b* and *c* being bent into form from a single piece of tubing and the bottom bar *d* connected at its opposite ends to the ends of the 45 end bars *b* and *c* by mitered joints *e*. The end bar *c* is provided with hinge-plates *f*. The longitudinal line or strand wires forming the filler for the gate frame are designated *g*, and the stays or pickets forming the 50 filler, and which cross the strand or line wires beneath the same, are designated *h*. The strand or line wires are preferably spaced at graduated distances from each 55 other, as shown in Fig. 29, but the stays or picket wires have a uniform spacing; the object of which is that the strand or line wires in the gate frame should correspond approximately to the spacing of the strand 60 or line wires in the fence fabric with which the gate is associated when in use, and it is also preferable to have the spacing of the stay or picket wires correspond approximately to the spacing of the stay or picket 65 wires in any such fence fabric. Before the

gate is subjected to the operations of the wire-connecting mechanisms in my improved machine, the strand or line wires *g* are secured to the opposite end bars *b* and *c*, by having their ends passed through openings or perforations in said bars, and their ends headed as at *i*. The stays or picket wires *h* are secured in like manner to the gate frame; that is to say, they are placed crosswise of the strand or line wires *g* with their opposite ends secured to the top and bottom bars *a* and *d* of the frame, the ends of said stays or picket wires being passed through perforations or openings in said bars *a* and *d*, and their opposite ends headed as at *j*. When the wires *g* and *h* have been secured to the gate frame in the manner just explained, if there is any slack left in the wires it is taken up by the attachment of the staple-like members or tie-wires *k*, the operation of connecting the staple-like members or tie-wires to the intersections of the wires *g* and *h* kinking said wires in the manner shown at *l* in Fig. 32. These staple-like members *k*, the making and attaching of which will be more fully explained, 70 secure the intersections of the wires *g* and *h* by having the arcuate portions *m* of said staple-like members passed diagonally across the intersections of wires *g* and *h*, with the ends *n* passed concentrically around the wires *h* on opposite sides of the wires *g*, as shown in Figs. 30, 31 and 32, the stapling of the wires making the wires 75 a unit with the frame, thereby reinforcing 80 the frame and strengthening said frame. When the gate frame is placed upon the carrier or movable support, it is preferably laid upon the support in the manner shown in the figures, especially in Fig. 13, although in this 85 figure only a part of the gate frame is shown. In this position the end bar *c* with the hinge plates *f*, is placed foremost in the machine, and precedes the movement of the 90 remaining portions of the frame, as said 95 frame is advanced by the carrier or movable support through the machine; and when so placed the stay or picket wires *h* will be 100 below the strand or line wires *g*, obviously 105 so, because the staple-like members or tie-wires *k* are driven from above across the 110 intersections of said wires *g* and *h*.

The carrier or movable support includes the shaft 54, previously referred to, which is operated when it is desired to move the 115 carrier forwardly either by the use of the operator's lever 265, the spring pressed 120 detent or pawl 266 and the tooth 263, when the frame is being advanced preliminarily to 125 operative position, or by means of the eccentric 50, previously referred to on the timing shaft 45, and other parts to be described, also a shaft 89 located at a suitable point in the rear of the machine. In the 130 figures, particularly Figs. 3, 4, 5, and 6, the

machine is foreshortened, that is, for the purpose of illustration only, the shaft 89 is at a point considerably forward of what it would be in the actual machine, for the reason that the carrier must be of a sufficient length to support the longest gate frame, approximately 16 ft. long, and it will be understood that it will also take care of gates of the smallest size, approximately 3 ft. and from there on up to 16 ft. The shafts 54 and 89 each have secured thereon a pair of sprocket wheels 90, said sprocket wheels being suitably spaced apart on the said shafts, as best seen in Figs. 1, 2 and 13, and connecting said sprocket wheels are sprocket chains 91, the upper runs of said chains passing over the lower cross frame 36, and the lower runs of the chains passing through openings 91^a in said cross frame 36 (see Figs. 1 and 2).

To automatically drive the shaft 54 forwardly, or in a direction which will move the sprocket chains 91 so as to advance the gate in the machine, after the preliminary movement of the chains 91 with the gate thereon, through the operation of the toothed wheel 263 by means of the operator's lever 265 and the spring pressed detent or pawl 266, there is secured on one end of the shaft 54 a ratchet-toothed-wheel 92, said wheel being located between plates 93 forming a yoke between which, and to which, is pivotally secured the pawl 94, adapted to engage the teeth of the ratchet-toothed wheel 92, for rotating the shaft 54 in a step-by-step movement. This pawl is normally held in operative position by means of a spring 95 (see Fig. 13). Pivotally connected to the plates 93 forming the yoke, is a pitman or connecting rod 96, the upper end of which has connection with a strap 97 encircling the eccentric 50 and adapted to be operated thereby. During each stroke or up and down movement of the pitman or connecting rod 96, the shaft 54 is partially rotated by means of the pawl and ratchet wheel referred to. A gate is first laid across the chains 91 in a position in the rear of the wire-connecting mechanisms, to be described; the operator will grasp the lever 265, release the spring pressed detent or pawl 266 from the toothed wheel 263, swing it up and back, allowing the detent or pawl 266 to enter a tooth in the wheel 263, moving the lever forward, partially rotating the shaft 54. He will continue this alternate forward and backward movement of the lever 265, advancing the chains 91 in a step-by-step movement until the gate has been advanced to a position in the machine to be engaged by friction guiding and claiming means, in which position the first row of intersections of the cross wires will be in the rear of, but in close proximity to the down and up movement of the wire-

connecting mechanisms, when he will discontinue the operation of the shaft 54 through the lever 265 and the toothed wheel 263, setting the parts in motion which will operate the shaft 54 in a step-by-step movement, through and by means of the ratchet toothed wheel 92 and the connections therefor with the power just previously described. The chains 91 are connected by a cross-bar 96, (see Figs. 4, 5, 6 and 13), and said cross-bar has connected thereto the angular brackets 97 which have V-shaped notches in their acting faces in which is fitted and has a bearing, the end bar 6 of the gate frame, assisting the chains during their operation, in moving the gate forwardly in the machine. When the gate has reached a position in the machine where the last row of intersections of the cross wires have each been connected by a staple-like member or tie-wire, the shaft 54 is automatically stopped and it remains in such an inoperative condition until the operator makes certain connections which will reverse the operation of the shaft 54, returning the chains 91 and the cross bar 96 to a position for receiving another gate. The shaft 54 is automatically stopped, by means which I will now explain:—

On the shaft 54 adjacent the ratchet-wheel 92 is loosely carried a disk 98 having a cam-like peripheral surface 99, and a notch 100. Said disk-like member 98 is also provided with an arm extension 101 having several perforations 102 whereby a bar 103 may have an adjustable connection therewith, the opposite end of said bar 103 being connected with the lower end of a lever 104 fulcrumed on the end of shaft 160, the opposite end of the lever 104 having a projection 106 which normally stands in the path of movement of an arm 107 secured to the chain 91 on the left-hand side of the machine, looking from the front. A spring 108, one end secured to the lower end of the lever 104, and its opposite end secured to a frame part, holds the lever in engaging position shown in Fig. 4 as well as holds the disk-like member 98 in the inoperative position shown in Fig. 18. When the arm 107 through the movement of the chain 91 engages with and moves the lever 104, said lever 104 through the connecting bar 103 will oscillate the disk-like member 98 on the shaft 54, moving the cam-like surface 99 of the disk from beneath the pawl 94, causing the surface 109 of said disk-like member to move up under an extension of the pawl 94, raising said pawl, and holding the same from engagement with the ratchet teeth of the wheel 92, the slot 100 in the disk-like plate moving to a position which will allow the bar 110 (see Figs. 1 and 18) to enter the slot 100 holding the pawl 94 in disengaged relation, as stated, placing

the parts in inoperative relation. The bar 110, best seen in Fig. 1, is slideable in a bracket support 111 and moved through the action of a spring 112, when the slot 100 of the disk-like plate 98 is brought opposite or coincident with the bar 110, said spring 112 having one end attached to an operator's lever 113 and its opposite end secured to an extension of the bracket support 111, the lower end of the lever 113 formed with a bifurcation straddling a pin in the bar 110. The ratchet wheel 92 cannot be operated when resting upon the surface 109 of the disk-like plate 98, although when the parts 15 are in this position there is nothing to interfere with the pawl 94 riding forward and back over the teeth of the ratchet wheel 92, but without engaging the same, and it is during this inoperative relation of the 20 ratchet and pawl means for driving the shaft 54, that said shaft may, by means which will now be described, be rotated in a reverse direction for the purpose of returning the chains 91 and the bar 96 to initial 25 or receiving position.

The pulley wheel 53, which has been described as being loosely carried on the shaft 54, has a hub extension provided with a clutch part 114 and said clutch part is 30 adapted to be engaged by a clutch part 115, forming a part of or attached to a sleeve 116 having a spline and groove connection with the shaft 54, said sleeve having connected thereto the yoke 117 of an operator's 35 lever 118 pivoted at its lower end at 119 to a casting or frame part 120, secured to the casting or frame part 33, (see Figs. 2 and 3). It is obvious that by operating the lever 118 to slide the sleeve 116 on the shaft 54, 40 a clutch engagement may be brought about between the clutch parts 114 and 115 for connecting the pulley 53 with the shaft 54, which will operate said shaft, but in a reverse direction to that just previously described, and through such movement return 45 the chains 91 and the bar 96 to gate-receiving position. When the chains 91 and the bar 96 have reached a gate-receiving position, the lever 118 is automatically moved for disconnecting the clutch part 115 from the 50 clutch part 114, bringing the shaft 54 to a standstill, preparatory to the placing of another gate on the carrier or movable support to be brought to position for operation 55 thereupon by the wire connecting mechanisms. To accomplish this automatic separation of the clutch parts 115 and 114, a bar 121 which has one end connected with the lever 118 has its opposite end connected 60 to an angular bar 122, which forms a lever and is fulcrumed at 123. The rear end of said bar 122 has connected thereto a rod 124, and on said rod at a suitable point, is a collar-like member 125, which is in the path 65 of rearward movement of an extension of

the bar 96 and is adapted to be engaged thereby for the purpose of moving the rod 124 in a direction which will oscillate the bar 122 on its fulcrum, moving the bar 121 in a direction which will operate the lever 118 to separate the clutch part 115 from the clutch part 114. The parts having assumed this position and the machine being ready for another gate, upon the same being placed on the chains 91, as previously described, in the rear of the wire-connecting mechanisms, the operator will operate the shaft 54 for advancing the chains 91 with the gate thereon to preliminary position, through the lever 265, spring pressed detent or pawl 266 and toothed wheel 263, and when the gate has been moved to such a position, the operator will move the lever 113, (see Fig. 1) in a direction which will move the bar 110, releasing it from the slot 100 in the disk-like plate 98, allowing the spring 108 to retract moving the disk-like plate 98 to the position shown in Fig. 18, bringing the cam-like surface 99 of said disk-like plate beneath the pawl 94, allowing it to drop into 90 engaging relation with the teeth of the ratchet wheel 92, the retraction of the spring 108 also moving the lever 104 into position to be again operated through the engagement of the arm 107 therewith. 95 Upon the release of the bar 110 from the notch 100 in the disk-like plate 98 and the return of the said disk-like plate to the position shown in Fig. 18, the engaging end of the bar 110 will bear against the inner face 100 of said disk-like plate, as shown in Figs. 1 and 18.

In describing the friction guiding and clamping means for the gate, and the posit- 105 ing mechanism, with which the friction guiding and clamping means are associated, I will first describe the respective friction guiding and clamping means, the manner of their support, the elements included in the posit- 110 ing mechanism, and the manner in 110 which the same are operated just previous to the operation of the wire-connecting mechanisms, to be described:

On one side of the machine, preferably on the left-hand side of the machine looking at the front, and in alinement with the wire-connecting mechanism, there is provided a friction clamp 126 including the sections 126^a and 127 pivoted together at 128. The section 126^a of said clamp is secured to 120 a member 129 and is formed with a concave gate-frame friction-gripping surface 131, whereas the section 127 is movable thereon and it also is provided with a concave gate-frame friction-gripping surface 130 together with the section 126^a adapted to receive and engage the bottom bar *d* of the gate frame (see Figs. 9, 10 and 13). Extending up from the section 126^a of the clamp, and through the other section 127, is a stem 132 130

having a nut 133 on its upper end, and between a collar 134 on said stem adjacent the nut 133, and the section 127 of the clamp, is carried a spring 135 coiled about the stem 132 and yieldingly holding the section 127 of the clamp in lower engaging position. When the gate frame, through the movement of the chains 91, is brought into engagement with said friction clamp, the end 10 of the gate may find easy entrance between the clamping surfaces of the sections 126^a and 127, by reason of the bevel edges 127^a of said sections, (see Fig. 33), the spring 135 yielding to the entrance of the frame, 15 while at the same time acting to frictionally hold the section 127 against the bottom bar *d* of the frame, as shown in Fig. 10, and yet not so firmly but what the gate may move through the clamp, as the chains 91 20 are operated to advance the gate in the step-by-step movement through the machine. On the opposite side of the machine to that on which is located the clamp 126 just described, and in alinement with said clamp and wire-connecting mechanisms, there is provided a grooved friction guiding roller 136, best seen in Figs. 7, 13 and 34. The function of this grooved roller is to bear against the top bar *a* of the gate frame, assisting the friction clamp 126, previously described, in holding and guiding the frame during its movement through the machine. This roller 136 is carried by an arm 137 fulcrumed at 138 on a support 139 secured 30 to a transversely disposed vertically movable, angularly shaped bar 140. A spring 141 serves to hold the roller 136 yieldingly pressing against the frame, in the position shown in Fig. 13. The member 129 supporting the movable sections 126^a and 127 of the clamp previously referred to, is also secured to and movable with said transverse movable bar 140. This bar 140 is guided in its vertical movement by means of rods or 40 bars 142, each of which is movable in guide boxings 143, a pair of boxings being provided for each rod or bar and spaced above each other as shown in Figs. 2 and 5, and secured to the front wall of the lower cross frame 36, also a bearing block or foot 126^b connected with or forming a part of the lower half of 126^a of said friction clamp, and bearing slidably against the end casting or frame 34, (see Figs. 9 and 10). Said rods or bars 142 are provided with stops 144 which engage with the lower guide boxings 143 and form a stop for the movable cross bar 140, when said bar has reached the limit of its downward movement. The 50 bar 140 is moved down and up through and by means of the cam wheel 49 previously referred to, carried on the timing shaft 45, said cam wheel engaging a roller 145 carried by an arm 146 secured to a rock-shaft 55 147, said rock-shaft journaled in bearings or boxings 148 secured to the upper front wall of the cross frame 35, (Figs. 1, 2, 5 and 7). To the opposite ends of this rock-shaft 147 are secured crank arms 149 to which are pivotally connected coupling members 150 and adjustably connected to said coupling members are pitman or connecting rods 151 which at their lower ends are adjustably connected to coupling members 152 which in turn have a pivotal connection with bracket members 153 secured to the movable cross bar 140. It is obvious that the cam 49 riding against the roller 145 will oscillate the arm 146, rocking the shaft 147, which movement will 70 raise and lower the pitman or connecting rods 151 and with said rods the movable cross bar 140 and the friction guiding and clamping means for the gate frame, previously described as being secured to 75 said movable cross bar 140. The cam 49 is timed in its relation to the other working parts of the machine, so that the cross bar 140 is lowered at a time when the gate has been advanced to a position in the machine, 80 with a row of intersections of the cross wires in alinement with the wire connecting mechanisms to be positioned for the attachment of the staple-like members or tie-wires, and raised so that the frame may be 85 advanced a predetermined distance through the machine for the application of the next row of staple-like members or tie-wires. 90

The friction guiding and clamping means 126 and 136 are located as stated upon opposite sides of the machine, the roller 136 being adjustable laterally on its support to provide for gate frames of different heights. When the gate has been moved to position 100 a stay wire *h* across the path of movement 105 of the wire-connecting mechanisms, the stay will extend crosswise of the machine in alinement with the clamp 126 and the roller 136, the clamp 126 being so positioned that the bottom bar *d* of the gate frame, at the 110 point where the stay wire *h* is joined thereto, will have a predetermined position with respect to the first set of wire-connecting mechanisms, insuring the first intersection 115 of the cross wires at this side of the machine assuming a position directly in the path of movement of the first set of movable parts of said connecting mechanism. This accomplished, the position of the remaining intersections of the stay wire with 120 the other cross wires, with respect to the other wire connecting mechanisms, is assured.

While the gate is supported upon and is movable with the chains 91, the weight of 125 the frame is mainly borne by the rear spaced longitudinal supporting bars 152^a and the front spaced longitudinal supporting bars 153^a, it being understood that when the frame is positioned and during its initial movement 130

in the machine, the frame of the gate will rest upon and move on the bars 152^a and through the friction guiding and clamping means, previously described, and as soon as the 5 frame reaches a position for the attachment of the first row of staple-like members or tie-wires, and during the further movement of the gate through the machine, the weight of the frame will be partially borne 10 by the supporting bars 153^a which will finally assume the full support of the gate as it leaves the machine, and from which the operator will take said gate. The cross bar 96, previously described as being attached 15 to the chains 91 and having the bracket members 97 secured thereto against which the end bar *b* of the gate frame bears, is movable above the longitudinal supporting bars 152^a, as shown in Fig. 13. The inner 20 ends of the forwardly disposed supporting bars 153^a are connected to bracket members 154, which are in turn suitably secured to the vertically movable cross bar 140. The forward end portions of the rear supporting 25 bars 152^a are connected by being bolted or otherwise suitably secured to a vertically movable cross bar 155 (see Figs. 7 and 13) said bar extending crosswise of the machine and located to the rear of the lower cross 30 frame 36. The gate frame resting upon the forward and rear movable supporting bars 153^a and 152^a, it is obvious that when said bars are lowered or raised, that the gate frame will also be lowered and raised there- 35 with, for the proper positioning of the cross wires for the attachment of the staple-like members or tie-wires thereto. The front supporting bars 153^a through their supporting connections 154 with the cross bar 140 40 will permit said front bars to be lowered and raised directly through the movement of the said bar 140. The cross bar 155, to which are secured the supporting bars 152^a, is lowered and raised in unison with the 45 cross bar 140, and operated therefrom. The means employed for lowering and raising the cross bar 155 from the cross bar 140, comprise a pair of bell-crank levers 156 which are carried on the shaft 54, one exten- 50 sion of each of said bell-crank levers having a pivotal connection with the brackets 153 secured to the cross-bar 140, and the other extensions of said bell-crank levers each having a pivotal connection with a longitudinally movable bar 157; said bars extending forwardly and rearwardly of the machine and passing through openings 158 in the front wall of the lower cross frame 36. The longitudinally movable bars 157, 55 at the rear of the cross-frame 36, have pivotally connected thereto an extension of bell-crank levers 159, said levers secured to said rock-shaft 160, the opposite ends of which are journaled in suitable bearings or 60 boxings on the end castings or frames 33

and 34. The other extensions of the bell-crank levers 159 are pivotally connected to links 161 which in turn have a pivotal connection with the vertically movable cross bar 155 to which are secured the supporting 70 bars 152^a. It is obvious that when the cross bar 140 is lowered it will rock the bell-crank levers 156 on the shaft 54 moving the bars 157 in the direction of the arrows shown in Fig. 7, and that such movement of the bars 75 157 will in turn rock the bell-crank levers 159, which will lower the links 161 drawing down the cross bar 155 and the supporting bars 153^a and 152^a, whereby the forward and rear supporting bars 153^a and 152^a will be 80 lowered in unison. The upward movement of the cross bar 140 will impart a reverse movement to the parts just described, which movement will elevate or return to their normal positions the supporting bars 153^a 85 and 152^a in unison. The rear ends of the supporting bars 152^a are secured to a cross bar 162, (see Figs. 3, 4, 5, and 6), said cross bar being similar to and having the same movement imparted thereto as the cross bar 155 to 90 which the forward portions of the supporting bars 152^a are secured. The cross bar 162 is lowered and raised by means of links 163 having pivotal connection thereto and in turn being pivotally connected to extensions 95 of bell-crank levers 164 carried by a rock-shaft 165, journaled in any suitable support, the other extensions of said bell-crank levers having a pivotal connection with the longitudinally movable bars 157. Although not 100 shown, the forward ends of the supporting bars 153^a are secured to a cross bar similar to the cross bar 162 just referred to, and the same is adapted to be lowered and raised through link and bell-crank connection with 105 the forward ends of the longitudinally movable bars 157. Through a mechanism of this character, the supporting bars 153^a and 152^a may be of any suitable length, the longitudinally movable bars 157 being of a corresponding length and connected through bell-crank levers and links, to adapt the inner and outer ends of all of the supporting bars to be lowered and raised in unison. 110

Movable in a horizontal direction forwardly of the machine, coincident with and during the lowering of the cross bar 155, and supporting bars 152^a and 153^a, and returnable to its normal position during the upward movement of the bar 155 and said 115 supporting bars, is a cross bar 166 to which are secured the rear ends of a plurality of bars 167, the forward portions of said last-mentioned bars being movable through slots 168 in a guiding bar 169 secured crosswise 120 of the machine and on the upper shelf-portion of the cross frame 36, (see Figs. 7, 11 and 14). Pivotally connected to the forward ends of the bars 167 are wire-guiding fingers 170 the forward ends of which have 125 130

angularly-shaped faces producing the wire-receiving crotch 171, (see Fig. 11). Springs 172 together with pins 173 yieldingly hold the wire-guiding fingers 170 and yet allow 5 the same to have down and up movement through the engagement of certain movable parts of the wire connecting mechanisms during the operation of such parts, when applying tie-wires. The opposite ends of 10 the cross bar 166 are movable in guides 174 secured to and extending rearwardly from the shelf portion of the lower cross frame 36. These guides permit sidewise movement of said bar 166, and to prevent end- 15 wise movement thereof, pins 175 are secured to the cross bar 166 upon each side of the guides 174 and bear thereagainst, as shown in Fig. 14. To retain the cross bar 166 and the wire-guiding fingers 170 connected 20 thereto, in a rearward inoperative or disengaging position, stop fingers 176 are provided, pivoted at their lower ends at 177 to a frame 178 secured to the lower cross frame 36, the upper ends of said stop fingers 25 176 being positioned in front of the cross bar 166 and bearing against the front edge thereof. The stop fingers 176 at their lower ends have crank-extensions 179 to which are connected the lower ends of rods 180, 30 the upper ends of which are secured to the rear supporting bars 152^a, (see Figs. 7 and 14). Connecting the cross bars 155 and 166 are springs 181. When the bell-crank levers 159 are operated to lower the cross bar 155 35 and with it the supporting bars 152^a, the rods 180 will be lowered through the movement of the bars 152^a, oscillating the stop fingers 176 on their pivots 177, moving the upper ends of said stop fingers away from 40 the cross bar 166, allowing the springs 181 to retract, moving the bar 166 toward the cross bar 155, advancing the wire-guiding fingers 170 connected thereto, to wire engaging and guiding position. When the 45 cross bar 155 is raised and the bars 152^a are also raised, said last-mentioned bars will lift the rods 180 returning the stop fingers 176 to their normal positions, and during such movement force the bar 166 rearwardly and 50 with said bar the wire-guiding fingers 170, as will be understood. There are other wire-guiding means, to be described, in connection with the wire connecting mechanisms, which coöperate with the wire-guiding fingers 170 for properly positioning the cross wires preliminary to and during the operation of the wire connecting mechanisms. 55 The wire connecting mechanisms which will now be described, the movable parts of 60 which are all mounted on the machine above the path of travel of the gate through the machine, comprise a series of sets of tie-wire severing devices, devices for forming the tie-wires into staple-like members, and 65 punches or tools for driving and locking

the staple-like members about the intersections of the cross wires in the gate frame; and associated with said wire-connecting mechanisms are suitable wire guiding means, which coöperate with the wire guiding fingers 170 for properly positioning the wires preliminary to the operation of the wire connecting mechanisms thereupon. Certain parts or devices included in the wire connecting mechanisms are operated by 70 means of a vertically movable plate 182, and certain other of the parts or devices included in said wire connecting mechanisms are operated by a vertically movable plate 183. The plate 182 moves up and down on 75 the front face of the vertical wall of the upper cross frame 35, and the plate 183 moves up and down on the front face of the plate 182, both of said plates, as best seen in Fig. 22, are located and movable between the front wall of the cross frame 35 and the stationary cross bar 39. The plate 182 has secured thereto on its upper edge a series of coupling members 184, and to said members are pivotally connected coupling members 185 to which are adjustably connected pitman or connecting rods 186 and they in turn at their upper ends are adjustably connected to eccentric straps 187 operated by the eccentrics 48, previously referred 80 to. The coupling members 185 are connected to the coupling members 184 through the pins 188 which are movable up and down in vertical slots 189 in the coupling members 184, best seen in Figs. 22. Owing 85 to the continuous rotation of the timing shaft 45, when the plate 182 has been moved upwardly into the position shown in Fig. 22, said plate 182 must remain stationary for a short period of time, to allow for the infeed 90 of the tie-wire stock, when the plate 182 may be lowered, moving with it the severing means for cutting short sections from the tie-wire stock which produce material for the staple-like members used to connect the 95 cross wires in the gate frame; therefore, the movement allowed for the pins 188 in the slots 189 is sufficient to permit said pins to descend slightly during the rotation of the timing shaft 45 before the actual operation 100 of the lowering of the plate 182 begins, and it is during this interval of time that the tie-wire stock is fed in, as stated. The plate 183 has secured thereto on its upper edge a series of coupling members 190, and 105 to said members are pivotally connected coupling members 191 to which are adjustably connected pitman or connecting rods 192 and they in turn at their upper ends are adjustably connected to eccentric straps 193 110 operated by the eccentrics 47, previously referred to, on the timing shaft 45. The connections between the timing shaft 45 and both of said plates 182 and 183 may be seen 115 upon examination of Figs. 1 and 2. 120 125 130

As the sets of connecting mechanisms, including the severing, forming and driving means, are identically the same, the description of one set will suffice for all, reference being had to Figs. 21 to 28, inclusive. Secured to the lower front face of the plate 182 is a preferably rectangularly shaped tubular member 194, which for convenience will be designated by its shop term, the hollow cutting and bending block, this block extending down and being movable across the front face of the stationary angular bar 37, previously referred to, and provided with a cutting or severing part 195 adapted 5 for severing a section from the tie-wire stock *a* projected through the end 196 of the guiding tube 38 through which the tie-wire stock *a* is fed, the end of the tube serving as a cutting member which co-operates with 10 the cutting or severing part 195 on the block 194. The block 194 is guided in its down and up movement by means of the guiding bracket 197, said bracket being secured by means of bolts to the front wall of the cross frame 35. The lower end of the tubular cutting block 194 serves as a die-member and clamp which co-operates with a die-member 198 held in position against the front face of the lower cross frame 36. The means 15 for holding the die-member 198 comprises an adjusting and retaining screw 199 passing through a cross-bar 200 and bearing against the front face of the die-member 198, and an adjusting and retaining screw 201 passing through a block 202 and engaging the lower end of said die-member 198. The upper horizontal face of the die-member 198 is provided with the transverse wire receiving grooves 203 and 204, the former adapted to receive and form a seat for the stay wires *h* in the gate frame, and the latter adapted to receive and form a seat for the strand or line wires *g* in the gate frame. It is understood that the cross bar 200 is provided with means such as the adjusting and retaining screws 199 for each of the die-members 198, and that there is a block 202 for each die-member 198, unless where the die-members are close together it 20 is necessary to employ a block such as 202 for several of the die-members 198. The block 194, previously described as preferably rectangular in cross-section and tubular, is provided with an obliquely disposed 25 opening or slot 205 and having movement in this slot is an anvil 206, said anvil comprising a rectangularly shaped elongated bar having the forward beveled upper edge 207 and the wire guiding slot 208 in the end 30 thereof. This anvil 206 is disposed normally at an incline and is adjustably carried in the slotted end 209 of an arm 210, said arm having pivotal connection at 35 with the stationary cross bar 39, previously 40 described. The position of the acting end

of the anvil 206, being that end having the beveled portion 207 and the wire guiding slot 208, when in operative position relative to the cutting and forming of the tie-wire stock, is determined by the adjusting screw 70 45 212 with which the arm 210 will engage when the anvil 206 has been moved to operative position, said adjusting screw 212 having connection with a plate extension 213 50 extending up from the guiding bracket 197 75 and connected with the stationary cross bar 39 through the bracket or casting 214. The adjustment of the screw 212 will regulate 80 the movement of the arm 210, limiting or increasing the movement of said arm, and by means of an adjusting screw 215 the anvil may be adjusted in the slotted end portion 209 of the arm 210. The anvil 206 after the block 194 has severed a section 85 from the tie-wire stock and formed said section of wire into a staple-like member over the anvil, is moved out of the way by the punch or tool employed for driving the staple-like member across the intersection of the cross wires in the frame; however, the 90 slot 205 in the block 194 is of sufficient length so that the block 194 may move across the anvil during the formation of the tie-wire section into a staple-like member, when the anvil is engaged by the punch or tool 95 moving it out of the way and holding it in such position during the complete downward stroke of the punch or tool and when the anvil is released through the upward movement of the punch or tool, a spring 216, 100 one end of which is connected to a finger 217 projecting from the arm 210, and the opposite end of which is connected to the plate extension 213, will return the anvil and arm to operative position, the outward 105 movement of the anvil and arm being against the tension of this spring. The punch or tool to which reference has been made, is designated 218, the lower portion 110 of which is movable longitudinally in the 115 tubular block 194 and its upper end portion is adjustably carried in an opening 219 in the vertically movable plate 183. Said punch or tool has longitudinal adjustment in the plate 183 through and by means of the adjusting screw 220 and the same is held in fixed adjusted position by means of the adjusting screw 221. The lower end portion of the punch or tool 218 is preferably 120 rectangular in cross-section, corresponding to the opening through the block 194 and the lower end of said punch or tool is provided with a concave seat 222, and bevel portions 223 for said concave seat adapted to engage and receive the arcuate 125 portion *m* of the staple-like member *k*, when it is formed, which retains the staple-like member during the driving of the staple-like member across the intersection of the cross wire and against the die-member 198, 130

whereby the staple-like member is caused to engage the cross wire in the manner seen in Figs. 30 to 32 both inclusive. The operation of severing, forming and driving the tie-wire is best seen in Figs. 23, 24 and 25, wherein the tie-wire stock *o* is first projected across the lower end of the block 194 and through the guiding slot 208 in the anvil 206. The plate 182 starts moving 5 downwardly in advance of the plate 183, causing the severing or cutting part 195 on the block 194 to engage with and sever a short section of wire from the tie-wire stock *o*. The continued downward movement of 10 the block 194 will bear the short section of the tie-wire over the anvil 206 in the manner shown in Fig. 24, forming the staple-like member *k* with the arcuate portion *m*, within the block. At or about the completion 15 of the staple-like member *k* from the short section of tie-wire stock, the plate 183 is given its initial downward movement, causing the punch or tool 218 to move downwardly, the movement of the punch 218 and the block 194 now being simultaneous, 20 the end of the block 194 continuing its movement toward the die-member 198 in advance of the punch or tool and the bevel end 223 of the plunger 218 following on and engaging with the bevel surface 207 of 25 the anvil 206 riding over the anvil and forcing the anvil outwardly, swinging it and the arm 210 on its pivot 211, the concave seat 222 of the plunger engaging the arcuate portion *m* of the staple-like member *k*, and 30 said staple-like member being retained within the block 194, the block 194 with the staple-like member *k* and the plunger 218, continuing their movement until the block 35 194 engages with the cross wires *g* and *h*, forcing them into the respective transverse grooves in the die-member 198 holding the same in a fixed relation between the lower end of the block 194 and the upper end of 40 the die member 198, in which position the punch or tool 218, forcing the staple-like member *k* downwardly, will drive said staple-like member across the intersection 45 of the wires *g* and *h*, causing the ends of 50 the staple-like member through their engagement with the die-member 198, to be wrapped about the wire *h* in the manner shown in Figs. 30 to 32, inclusive, after 55 which movement the plates 182 and 183 are raised substantially in unison and simultaneously.

The wire guiding means, previously referred to as associated with the wire connecting mechanisms, and coöperating with 60 the wire guiding fingers 170, comprise the plates 224 having the bifurcated ends 225 and the wire receiving slots 226. These plates are secured to and movable with the tubular blocks 194, to straddle the stay wire 65 *h* and guide the wire into the slot 226, posi-

tioning said wire in proper alignment over the die-members 198, so that when the ends of the blocks 194 engage with the wire *h*, the wire will be clamped between the ends of the blocks 194 and the die-members 198, 70 in the grooves 203 of said die-members 198. For guiding the longitudinal or strand wires *g* into the grooves 204 in the die-members 198, there are provided the normally up-standing plates 227, one for each die-member 198, said plates being located in front of said die-members 198 and pivotally connected at 228 to plates 229 secured to the cross bar 200, a spring 230 being employed 75 for holding said plates 227 in the normal position shown in Figs. 21 and 22. Each plate 227 has the bifurcated portion 231 and the wire receiving slot 232. When a stay wire *h* is being lowered or forced into engagement with the die-members 198, through the operation of the blocks 194, each of said strand or line wires *g* will be engaged by a block 194 and forced downwardly into the bifurcations 231 of the plates 227 and guided to the wire receiving 80 slots 232, which will properly position the strand or line wires *g* in their wire receiving grooves 204 in said die-members 198, whereby both the stay-wire *h* and the crossed strand or line wires *g* will be firmly held in 85 their proper transverse grooves in the die-members 198, by clamping action of the blocks 194 upon said die-members 198. When a row of staple-like members *k* have 90 been secured to the intersections of the cross wires *g* and *h*, and the frame with its wires has been elevated to its normal position, and as the frame is fed forward in the machine, the stay wire *h* will engage with the hinged 95 guiding plates 231, swinging them outwardly, allowing the stay wire to be moved without interference, and immediately upon the passing of the stay wire over the hinged plates 231, said plates through the action of the springs 230 will return said plates to 100 their normal wire receiving and guiding positions, shown in Figs. 21 and 22. In addition to the wire guiding fingers 170 previously described and the wire guiding plates 224 and 227, there is provided a wire 105 guiding finger 233 pivoted at 234 to the vertically movable plate 182, said finger 233 being bifurcated at its lower end (not shown), similar to the wire guiding plates 224 and 227. This finger has all of the functions of 110 the plates 224 attached to the blocks 194, except that the finger 233 is normally located as shown in Fig. 2, in a position to straddle the stay wire *h* adjacent the top bar *a* of the gate frame, and aline said stay wire with respect to the wire connecting mechanisms. It will be observed upon looking at Fig. 2 that the lower end of said finger is slightly curved and said finger is 115 normally retained engaging an adjusting 120

125

130

screw 235, by means of a spring 236. This finger 233, when it is lowered, is intended to straddle the stay wire *h* and aline said wire at this point in the frame with respect to the wire guiding plates 224, and if the frame should lag in its movement on one side or be slightly out of alinement, this finger by its engagement with the stay wire will tend to move it and the frame so as to properly align or square the frame of the gate with respect to the operative parts of the machine. Said finger is also yieldingly held to have movement relative to the gate frame, in the event that the top bar of the frame should not be straight, or present an irregular line from one end of the gate to the other; thus, there is provided the finger 233 for not only guiding and alining the stay wire adjacent the top bar of the frame, but also serving to square the frame with respect to the parts of the machine during its movement therethrough, also the movably supported wire guiding plates 224 for the body of the stay wire, as well as the yieldingly supported wire guiding plates 227 for the strand wires, said last-mentioned plates being movable to and from operative positions by contact of the stay wires after the operation of attaching the intersections of the stay wires *h* and strand wires *g*, also the wire guiding fingers 170 which move forward at or approximately the same time as the gate frame and wires *g* and *h* are lowered into wire connecting positions. Should the chains 91, by reason of wear or other causes beyond the control of the manufacturer, get out of alinement, causing one side or the other of the frame to lag during its movement through the machine, or the stay wires *h* be retarded, because of the slackness in the wires, or other causes beyond the control of the manufacturer, said wire guiding fingers 170 will move them forward into position to enter the slots in the finger 233 and plates 224 for action thereupon by the wire connecting mechanisms, previously described. By reference to Figs. 5, 11 and 22, attention is directed to the fact that the wire guiding fingers 170 have a pivotal relation with the bars 167, being yieldingly held in the upward position shown in these figures by the spring 172. As the bars 167 and the wire guiding fingers 170 move forwardly, the angular ends of the fingers 170 will engage with the stay wire *h*, causing it to ride up on the bevel ends of said fingers 170 and be seated in the crotch 171, being retained therein and approximately in line crossing the wire receiving slots 203 in the die-members 198, so that as the cutting and bending blocks 194 descend, lowering with them the guiding plates 224, the stay wire will be moved by engagement of the cutting and bending blocks 194 with said fingers, from off of the

angular ends of the wire guiding fingers 170 into said wire receiving slots 203 in the die-members 198. This movement is facilitated by the oscillation of the wire guiding fingers 170 through the engagement of the lower ends of the cutting and bending blocks 194, the springs 172 serving to return the wire guiding fingers 170 to their normal wire receiving and guiding positions upon the raising of the cutting and bending blocks 194. 75

I have previously stated that the tie-wire stock *o* is fed forward a predetermined distance to produce the sections from which are formed the staple-like members *k*, immediately after the blocks 194 have been raised to the position shown in Fig. 22 and during the interval of time when the pins 188 connected to the coupling members 185 are moving downwardly in the slots 189 of the coupling members 184. The mechanism employed for feeding the tie-wire stock *o* includes the series of pairs of feeding wheels 237 and 238, (see Figs. 19 and 20), the wheels 237 being carried upon and driven by the intermittently operated driving shaft 239, the same being journaled in suitable bearings formed in a housing 240. The wheels 238 are each provided with internal gear wheels 241, and said gear wheels mesh with and are driven by the toothed wheel 242 formed upon or secured to a shaft 243, said shaft also journaled in suitable bearings in the housing 240 and being driven from the shaft 239 through the gears 244 and 245. Each wheel 238 is adjustably held in its operative relation to its co-acting wheel 237, by means of the movable friction bearing 246 adjustably held by means of a bar 247 bearing thereagainst, said bar being retained in operative position by the adjusting screw 248. The tie-wires *o* are fed into the machine from a suitable reel or spool and passed through tubes 249 and 250, and from the latter tubes said tie-wires enter the guiding tubes 38, which lead from the feeding mechanism to the stationary cross bar 37. The shaft 239 is intermittently rotated from the time shaft 45 by means of the cam wheel 46 on said time shaft, said cam wheel engaging a roller 251 carried upon a vertically movable bar 252, said bar guided in its down and upward movement by guide boxings 253 and 254 on the end casting or frame 33. 255 is a coupling pivotally connected to the bar 52, and adjustably connected with said coupling is a pitman or connecting rod 256, which at its opposite end is adjustably connected with the coupling 257, said last-mentioned coupling having a pivotal connection with a yoke 258 loosely carried upon said driving shaft 239. On said shaft is a ratchet wheel 259, and pivotally connected with the yoke 258 is a pawl 260 adapted to engage the ratchet teeth of the wheel 259 for operating the same, and through it, the shaft 130

239 and said feeding wheels 237 and 238. Thus it will be seen that with each revolution of the time shaft 45, the cam 46 engaging the roller 251 will lower and raise the 5 bar 252 and with it the pitman or connecting rod 256, which will oscillate the yoke 258 on shaft 239, causing the pawl 260 to move the ratchet wheel 259 and with it the shaft 239 a distance which will feed in the tie-wire 10 stock σ sufficiently far to provide the section from which the staple-like member k is severed, and formed.

For preliminarily moving the chains 91 and a gate thereon to operative position in 15 the machine, a manually operated means, including lever 265, spring pressed detent or pawl 266 and toothed wheel 263 have been shown and described. It is preferable to operate the machine in this way, for the purposes stated, but if it is desired to bring the 20 gate to position automatically, one may use the mechanism shown in Fig. 35. In this figure the pulley 51, belt 52, pulley 53, clutch parts 114 and 115, together with lever 117 and parts associated therewith are used, for 25 returning the chains 91 to receiving position. However, for convenience the clutch parts 114 and 115 are located on the outside of pulley wheel 53 and the rod 121 is shaped 30 so as not to interfere with the belt 52. On the outer end of the drive shaft 40 is a loosely carried pulley wheel 267, said wheel being connected to pulley wheels 42 and 51 and may be operated either loose on the shaft 35 40 or with said shaft. The wheel 267 operates a twisted belt 268, and said belt operates a pulley wheel 269 loosely carried on the feed shaft 54, said last-mentioned wheel having a clutch part 270 adapted to be clutching 40 engaged by the clutch part 271 on the clutch 115.

To automatically position a gate in operative position in the machine, instead of bringing the gate forward by the manually 45 operated means previously described, the operator will move the lever 117 causing the clutch part 271 to engage the clutch part 270 and through such connection automatically revolve the shaft 54 and with it the chains 50 91 and a gate thereon. Upon the gate reaching its proper position in the machine, the lever 117 being moved to the neutral position seen in Fig. 35 will disconnect the clutch parts 270 and 271. It is understood that 55 when the pulley 269 is used to operate the shaft 54 forwardly, the pulley wheels 42, 51 and 267 are driven loosely on the shaft 40.

It will be understood that the wire connecting mechanisms, including the devices 60 for severing, forming and driving the staple-like members, are so mounted on the machine frame that they may be adjusted so as to meet any change in spacing of the filler wires in the gate frame, and that the wire guiding plates 224 and 227 may likewise be 65

adjusted. If the height of the gate frame is changed the wire guiding finger 233, as well as the guiding roller 136 and parts associated therewith may be and should be adjusted to meet such conditions. Changing 70 the number of the filler wires will necessitate a change in the number of the tie-wires σ and the feeding in of such wires σ may be regulated by releasing or applying pressure to any one of the friction bearings 246, as 75 may be desired.

It will be further understood that the initial or receiving position for a gate frame upon the feeding chains 91 will vary according to the length of gate in which the filler wires are to be attached. In other words, if a 16 foot frame is being operated upon it is obvious that the bar 96, the arm 97, and the collar 125 will have to be adjusted to meet such a condition; this being also 80 true if gate frames are worked upon which vary in length from a 3 ft. gate to a 16 ft. gate. A change in the spacing of the stay wires h will also require adjustment of some of the parts, such as for instance, the eccentric 50 on the end of the timing shaft 45, by means of which intermittent rotary motion is imparted to the ratchet-toothed wheel 92 and the feeding shaft 54. In the present illustration of the machine and gate, the stay wires h are spaced approximately 85 six inches apart, in which case moving the ratchet-toothed wheel 92 the distance of one tooth is equal to two inches of movement of the gate frame. The stays may be spaced 90 eight inches apart, twelve inches apart, or possibly other distances to correspond to the fence fabric in connection with which the gate is used, or possibly for some arbitrary reason, and when such change is made 95 in the spacing of the stay wires, a change must necessarily be made in the eccentric 50 to provide for a change in the movement of 100 the feeding shaft 54.

The blocks 202 in which are located the 110 adjusting screws 201 for securing the die-members 198, in the position shown in Figs. 21 and 22, are adjustably secured to the lower cross frame 36 by bolts 261 which pass through slots 262 in said blocks. This manner of securing the blocks 202 is to provide 115 against any undue pressure when the plates 182 and 183 are lowered, bringing the blocks 194 in operative engagement with the die-members 198 and the operation of the punch 120 or tools 218 upon the staple-like members k . If no means were provided for allowing the die-members 198 to give under any such undue pressure, there is a possibility that the mechanisms associated or connected to the 125 plates 182 and 183 might break, but by providing the blocks 202 with the slots 262, it will be observed that these blocks may give, allowing the die-members 198 to give, and 130 thus avoid any breakage of parts.

The operation of the machine, briefly stated, is as follows:

Assuming that the chains 91, constituting the carrier or movable support, and the bar 96 and arm 107, have been returned to a position in the rear of the machine for receiving a gate frame, to which have been secured the cross longitudinal strand or line wires *g* and the stay wires *h*, and the frame 10 has been placed crosswise of said chains with the end bar *b* engaged by the notched brackets 97, the operator to preliminarily position the gate frame with respect to the wire connecting mechanisms, may operate the lever 15 265 forward and back and through the spring pressed detent or pawl 266 and toothed wheel 263, impart a rotary intermittent forward movement to the feeding shaft 54, which will advance the chains 91 20 together with the gate frame thereon, into operative position in the machine, or he may bring about this result through the engagement of the clutch parts 270 and 271, the bottom bar *d* of the frame entering between 25 the sections of the friction and guiding clamp 126, and the top bar *a* of the gate will move against the guiding roller 136 which is yieldingly held in frictional contact therewith, as previously explained. When the 30 operator has brought the gate to its desired position, he will depress the foot lever 77, bringing about a clutch relation between the clutch parts 57 and 58 on the driving shaft 40, which will place said driving shaft in 35 operation through power connections with the driving pulley 42 thereon. The driving shaft 40 being placed in operation, power is transmitted from said driving shaft to the timing shaft 45 through the gears 43 and 44, 40 and said timing shaft will operate the eccentrics 47, 48 and 50 and the cam wheels 46 and 49, each and all being adjusted with respect to each other on said timing shaft so that the parts operated thereby will be 45 operated in timed relation to bring about the results shown. The rotation of the eccentric 50 will impart intermittent rotary movement to the feeding shaft 54 through the connections 92, 93, 94 and 96 therewith. By 50 such movement, the chains 91 are advanced, which will progressively and successively present the stay wires *h* to the wire connecting mechanisms for the attachment of the staple-like members *k* to the intersections of 55 said stay wires *h* and longitudinal cross wires *g*.

The gate having been advanced to a position which will bring the first stay wire *h* across and in line with the wire connecting 60 mechanisms, the cam wheel 49 on the timing shaft 45 will operate the lever 146 and it in turn will rock the rock-shaft 147, lowering the cross bar 140 through the connections 151 with said rock-shaft 147. The 65 lowering of the bar 140 will also lower the friction guiding and clamping parts 126 and the friction and guiding roller 136, together with the forwardly and rearwardly arranged gate supporting bars 153 and 152, through the connections which have been previously described, and which are very clearly shown in Fig. 7. As the gate frame is lowered through the parts referred to, the wire guiding fingers 170 will move forward to engage the stay wire *h*, 75 presenting said stay wire in the path of the wire guiding plates 224 connected to and movable with the cutting and bending blocks 194, so that as the plate 182 is moved downwardly, it will impart corresponding 80 movement to the cutting and bending blocks 194, which will sever sections from the tie-wire stock *o* and cause said sections to be bent into the form of staple-like members *k* within said blocks and over the anvils 206, in the manner best seen in Fig. 24. Upon the formation of the staple-like members the plate 183 is moved, causing the punches or tools 218 to descend, and engaging the anvils 206 will move the same out 85 of the path of travel of said punches or tools 218, permitting said punches or tools to engage with the staple-like members *k*, so that during the remainder of the downward movement of the cutting and bending 90 blocks 194 and the punches or tools 218, said cutting and forming blocks will engage with the intersections of the cross wires *g* and *h*, causing the wire *h* to ride 95 from off the angular ends of the wire guiding 100 fingers 170 into the wire receiving grooves 203 of the die-members 198, while the wires *g* will find their positions in the wire receiving grooves 204 in said die-members 198, the cross wires being engaged and firmly held 105 immovably between the ends of the cutting and forming blocks 194 and the die-members 198, the guiding plates 224 acting as the cutting and forming blocks 194 are lowered to guide the stay wire *h* into the 110 wire-receiving grooves 203 in the die-members 198, while the guiding plates 227 straddle the longitudinal wires *g*, guiding them 115 into position in said die-members 198. In this position, with the wires held firmly between the cutting and forming blocks 194 and the die-members 198, the punches or tools 218 moving slightly behind but at the same time with the cutting and forming blocks 194, will force the staple-like members *k* 120 diagonally across the intersections of the wires *g* and *h*, and the ends of the staple-like members engaging with the die-members 198, will be locked about the cross wires in the manner seen in Figs. 30 to 32, inclusive. 125

After the application of a row of staple-like members to the intersections of the cross wires *g* and *h*, the cross bar 140 is raised and with it the friction clamping 130

and guiding parts 126, the guiding roller 136, the supporting bars 152^a and 153^a, and the wire guiding fingers 170 are retracted, in the manner previously described, allowing the feeding means to be operated to advance the gate in the machine a distance of the spacing between the stay wires, when the next stay wire is brought to a position crosswise of and in alignment with the wire 5 connecting mechanisms, staple-like members *k* are severed and attached to the intersections of the second stay and cross wires, in the manner just previously explained; and this operation is continued 10 progressively and successively until each and all of the stay wire intersections of the cross wires in the frame are secured by the staple-like members *k*, at which time the arm 107 on one of the chains 91 has reached 15 a position where it will engage with the lever 104, operating said lever and the connections between it and the disk-like member 98 for discontinuing the operation of the pawl 94 upon the ratchet tooth of the 20 ratchet wheel 92, stopping the advance movement of the carrier through the machine, by which time the supporting bars 153^a have received the gate, from which the finished gate may be removed to the 25 stock. The parts of the machine are timed so that when the ratchet wheel 92 has been brought to inoperative condition because of the movement of the disk-like plate 98 through the engagement of the arm 107 30 with the lever 104, the tie-wire stock *o* has been fed with the end of such stock projecting across the path of movement of the cutting and forming blocks 194 and through the notches in the anvils 206, substantially 35 40 in the manner seen in Fig. 23, preparatory to the downward movement of the cutting and forming blocks 194 for severing said projected sections from the tie-wire stock for the formation of the staple-like members and connection of the same to the cross 45 wires in the frame.

When the lever 104 is engaged by the arm 107 and operated for the purpose of moving the disk-like plate 98 to a position which 50 will prevent the operation of the pawl 94 upon the ratchet-toothed wheel 92, the shaft 54 is stopped before the pawl 94 moves the ratchet-toothed wheel 92 the distance of the space between two teeth. In other words, the 55 toothed wheel 92 will stop with a tooth in a position to be again engaged by the pawl 94 upon the return of the disk-like plate 98 to inoperative position, whereby the pawl 94 again engaging said last-mentioned tooth of 60 the wheel 92, will move said wheel and with it the shaft 54 the remainder of the distance of the space between two teeth, so that when the operator has brought a gate to a position with the stay wire immediately in the 65 rear of the wire-connecting mechanisms, and

the disk-like plate 98 has been released and moved to a position to allow the pawl 94 to engage with a tooth in the ratchet-toothed wheel 92, said pawl will engage with a tooth and during its first movement advance the 70 toothed wheel 92 and the shaft 54 the remainder of the stroke, which slight movement will move the chains 91 and with them the gate so as to position the stay across and in alignment with the wire connecting mechanism. 75

After the discontinuance of the operation of the ratchet wheel 92 and the removal of the completed gate, the operator to return the chains 91 to a position in the machine to 80 receive another gate, will move the lever 117 for the purpose of bringing about a clutch relation between the clutch parts 114 and 115, which will impart continuous movement from the driving shaft 40 through the 85 belt 52 to the feeding shaft 54, reversing the movement of said feeding shaft and moving the chains 91 rearwardly in the machine. This movement will continue until the bar 96 connected with the chains 91 has reached 90 a position in the machine for receiving another gate, when an extension of said bar 96 will engage with the collar 125 on the rod 124 and operate said rod 124 to oscillate the lever-like member 122 and through it move 95 the lever 117 to disconnect the clutch parts 114 and 115, when the operator may again through the operation of the lever 265 and the toothed wheel 263, or through the clutch parts 270 and 271, advance the chains 91 and 100 with them a gate supported thereon, to a forward operative position in the machine. In this position the operator will move the lever 113 to disconnect the bar 110 from the notch 100 in the disk-like plate 98, allowing 105 this plate to assume a position which will permit the pawl 94 to engage with a tooth of the ratchet wheel 92 and operate said ratchet wheel to move it only a part of the distance of the space between two teeth in 110 the ratchet wheel, as aforesaid, whereby to position the first stay wire crosswise of and in alignment with the wire connecting mechanisms, and thereafter move the feeding 115 shaft 54 in a step-by-step movement to advance the gate through the machine, in the manner described.

It will be understood that the operator through the foot lever 77 and the hand lever 82 has full control of the clutch parts 57 120 and 58 on the driving shaft 40, so that he may start and stop the machine at will.

What I claim is:—

1. A machine for connecting the intersections of the filler wires of a gate frame, 125 including wire connecting mechanism, and means for moving a gate through the machine to present the intersections of said wires to said wire connecting mechanism.

2. A machine for connecting the inter- 130

- sections of the filler wires of a gate frame, including a row of spaced wire connecting mechanisms, and means for moving a gate through the machine to present the intersections of said wires to said wire connecting mechanisms. 70
3. A machine for connecting the intersections of the filler wires of a gate frame, including wire connecting mechanism, and 10 a movable carrier adapted to receive and advance said gate through the machine, whereby the intersections of said wires may be presented to said wire connecting mechanism. 75
- 15 4. A machine for connecting the intersections of the filler wires of a gate frame, including wire connecting mechanism, means for moving a gate through the machine to present the intersections of said wires to 80 said wire connecting mechanism, and guiding means for said gate frame. 85
5. A machine for connecting the intersections of the filler wires of a gate frame, including means for advancing a gate in a 20 step-by-step movement through the machine, wire connecting mechanism, and means for moving the gate laterally when the intersections of the filler wires are brought coincident with said wire connecting mechanism. 90
- 25 6. A machine for connecting the intersections of the filler wires of a gate frame, including wire connecting mechanism, longitudinally disposed supports for a gate 95 frame, and a carrier for moving a gate through the machine on said supports, whereby the intersections of said wires may be presented to said wire connecting mechanism. 100
- 30 40 7. A machine for connecting the intersections of the filler wires of a gate frame, including wire connecting mechanism, longitudinally disposed supports for a gate frame, a carrier for moving a gate through 105 the machine on said supports, guiding means for said gate frame, and means for moving said supports and guiding means when the intersections of said wires are brought coincident with said wire connecting mechanism. 110
- 35 50 8. A machine for connecting the intersections of the filler wires of a gate frame, including means for feeding a gate through the machine, wire connecting mechanism, 115 the movable parts of which are located on one side of the path of the movement of the gate, and means for arresting the movement of the gate when the intersections of said wires are coincident with said wire connecting mechanism. 120
- 40 60 9. A machine for connecting the intersections of the filler wires of a gate frame, including a row of spaced wire connecting mechanisms, means for moving a gate 125 through the machine to present the intersections of said wires to said wire connecting mechanisms. 130
10. A machine for connecting the intersections of the filler wires of a gate frame, including wire connecting mechanism, a carrier for moving a gate through the machine, means for preliminarily advancing the carrier with the gate thereon to operative position, other means for moving the carrier to present the intersections of the wires to the wire connecting mechanism, and means for reversing the movement of the carrier. 80
11. A machine for connecting the intersections of the filler wires of a gate frame, including wire connecting mechanism, means for supporting a gate in the machine, a carrier for moving the gate through the machine, means for preliminarily advancing the carrier with the gate thereon to operative position, other means for moving the carrier to present the intersections of the wires to the wire connecting mechanism, means for moving the supporting means laterally and with it the gate when the intersections of the filler wires are brought coincident with said wire connecting mechanism, and means for reversing the movement of the carrier. 90
12. A machine for connecting the intersections of the filler wires of a gate frame, including a series of sets of wire connecting mechanisms, each set comprising wire cutting and forming means and a punch, and means for moving a gate through the machine to present the intersections of said wires to said wire connecting mechanisms. 100
13. A machine for connecting the intersections of the filler wires of a gate frame, including a series of sets of wire connecting mechanism, each set comprising a stationary die member, and movable cutting and forming members and a punch, the cutting and forming members and punches movable toward and from said stationary die-members, and means for moving a gate through the machine and between said stationary die-members and said movable members of the connecting mechanisms, to present the intersections of said wires to said wire connecting mechanisms. 110
14. A machine for connecting the intersections of the filler wires of a gate frame, including a series of sets of wire connecting mechanisms, each set comprising wire cutting and forming means and a punch, a movable carrier for the gate, said carrier comprising endless chains on which the gate rests, means for moving said chains in one direction, and means for reversing the direction of movement of said chains. 120
15. A machine for connecting the intersections of the filler wires of a gate frame, in- 130

cluding a series of sets of wire connecting mechanisms arranged in a row, each set comprising wire cutting and forming means and a punch, means for moving a gate 5 through the machine to present the intersections of said wires to said wire connecting mechanisms, and guiding means for the gate frame with the intersections of the wires in a predetermined position, with respect to said wire connecting mechanisms.

16. A machine for connecting the intersections of the filler wires of a gate frame, including a row of spaced wire connecting mechanisms, guiding means for a gate located at the opposite ends of the row of said connecting mechanisms, and means for moving a gate through the machine and between said guiding means, to present the intersections of said wires to said wire connecting 15 mechanisms.

17. A machine for connecting the intersections of the filler wires of a gate frame, including a row of spaced wire connecting mechanisms, guiding means for a gate located at the opposite ends of the row of said connecting mechanisms, one of said guiding means being adjustable, and means for moving a gate through the machine and between said guiding means, to present the intersections of said wires to said wire connecting 20 mechanisms.

18. A machine for connecting the intersections of the filler wires of a gate frame, including a row of spaced wire connecting mechanisms, guiding means for a gate located at the opposite ends of the row of said connecting mechanisms, one of such guiding means comprising a member carried upon a pivoted support, the other of such guiding 35 means comprising friction clamping members, and means for moving a gate through the machine and between said guiding means, to present the intersections of said wires to said wire connecting mechanisms.

40 19. A machine for connecting the intersections of the filler wires of a gate frame, including a row of spaced wire connecting mechanisms, guiding means for a gate located at the opposite ends of the row of said connecting mechanisms, one of such guiding means comprising a grooved roller carried upon a pivoted support, the other of such guiding means comprising friction clamping members having a yielding 45 relation with respect to each other and adapted to receive a bar of the gate therebetween, and means for moving a gate through the machine between said guiding means, to present the intersections of said wires to 50 said wire connecting mechanisms.

55 20. A machine for connecting the intersections of the filler wires of a gate frame, including a row of spaced wire connecting mechanisms, guiding means for a gate located at the opposite ends of the row of said

connecting mechanisms, a movable support for said guiding means, whereby the same may be lowered and raised, and means for moving a gate through the machine between said guiding means, to present the intersections of said wires to said wire connecting mechanisms. 70

21. A machine for connecting the intersections of the filler wires of a gate frame, including a row of spaced wire connecting 75 mechanisms, supporting bars for the gate, means for lowering and raising said bars, guiding means for the gate located at the opposite ends of the row of said connecting mechanisms, a movable support for said 80 guiding means, connections between said movable support and the gate supporting bars, whereby the bars and guiding means may be lowered and raised in unison, and means for moving the gate through the machine between said guiding means, to present the intersections of said wires to said 85 wire connecting mechanisms.

22. A machine for connecting the intersections of the filler wires of a gate frame, 90 including a row of spaced wire connecting mechanisms, guiding means for a gate located at the opposite ends of the row of said connecting mechanisms, one of such guiding means having a predetermined position 95 in the machine relatively to the first set of wire connecting mechanisms, and means for moving a gate through the machine and between said guiding means, to present the intersections of said wires to 100 said wire connecting mechanisms.

23. A machine for connecting the intersections of the filler wires of a gate frame, including a row of spaced wire connecting mechanisms, guiding means for a gate located at the opposite ends of the row of said connecting mechanisms, one of such guiding means having a predetermined position in the machine relatively to the first set of wire connecting mechanisms, whereby the intersections of the wires may be properly aligned with respect to the wire connecting mechanisms when the gate is moved through the machine, and means for moving a gate through the machine, to present the intersections of said wires to said wire connecting 105 mechanisms, the guiding means adapted to frictionally engage the frame of the gate as it is moved through the machine. 110

24. A machine for connecting the intersections of the filler wires of a gate frame, including a row of spaced wire connecting mechanisms, guiding means for a gate located at the opposite ends of the row of said connecting mechanisms, one of such guiding 120 means having a predetermined position in the machine relatively to the first set of wire connecting mechanisms, the other of such guiding means being adjustably supported to adapt it to various heights of gates, 125 130

means for lowering and raising such guiding means in unison, and means for moving a gate through the machine and between said guiding means, to present the intersections 5 of said wires to said wire connecting mechanisms.

25. A machine for connecting the intersections of the filler wires of a gate frame, including wire connecting mechanism, means 10 for moving a gate through the machine to present the intersections of said wires to said wire connecting mechanism, and guiding and clamping means for opposite bars of the gate frame, such guiding and clamping 15 means adapted to frictionally engage the bars of the frame and yieldingly held in contact therewith to allow the gate to be moved therebetween.

26. In a machine of the character described, in combination, a carrier for advancing a gate through the machine, said gate containing a wire filler composed of uniformly spaced stay wires and other wires crossing the same, wire connecting mechanism, and means for imparting an intermittent movement to the carrier for progressively and successively presenting said stay 85 wires and the intersections of the cross wires therewith to said wire connecting mechanism.

27. In a machine of the character described, in combination, a carrier for advancing a gate through the machine, said gate containing a wire filler composed of 35 uniformly spaced stay wires and other wires crossing the same, wire connecting mechanism, means for imparting an intermittent movement to the carrier to successively present said stay wires and the intersections of 40 the cross wires therewith to said wire connecting mechanism, means for stopping the movement of the carrier after the operation of the wire connecting mechanism upon all of the stay wires, and means for reversing 45 the carrier to receiving position.

28. In a machine of the character described, in combination, a carrier for advancing a gate through the machine, said gate containing a wire filler composed of 50 uniformly spaced stay wires and other wires crossing the same, wire connecting mechanism, means for imparting an intermittent movement to the carrier for progressively and successively presenting said stay wires 55 and the intersections of the cross wires therewith to said wire connecting mechanism, and guiding means for said wires.

29. In a machine of the character described, in combination, a carrier for advancing a gate through the machine, said gate containing a wire filler composed of uniformly spaced stay wires and other wires crossing the same, wire connecting mechanism, means for imparting an intermittent 60 movement to the carrier for progressively 65

and successively presenting said stay wires and the intersections of the cross wires therewith to said wire connecting mechanism, means for lowering the gate and holding it in such position during the operation of the 70 wire connecting mechanism and then raising said gate, and guiding means for said wires.

30. In a machine of the character described, in combination, a carrier for advancing a gate through the machine, said gate containing a wire filler composed of uniformly spaced stay wires and other wires crossing the same, wire connecting mechanism, means for imparting an intermittent 80 movement to the carrier for progressively and successively presenting said stay wires and the intersections of the cross wires therewith to said wire connecting mechanism, means for lowering the gate and holding 85 it in such position during the operation of the wire connecting mechanism and then raising said gate, guiding means for the body of the stay wire operating thereupon during the lowering of the gate, and guiding 90 means for the other wires.

31. In a machine of the character described, in combination, a carrier for advancing a gate through the machine, said gate containing a wire filler composed of 95 uniformly spaced stay wires and other wires crossing the same, wire connecting mechanism, guiding means for the gate frame during its movement through the machine, means for imparting an intermittent movement to the carrier for progressively and successively presenting said stay wires and the intersections of the cross wires therewith to said wire connecting mechanism, and guiding means for said wires. 100

32. In a machine of the character described, in combination, a carrier for advancing a gate through the machine, said gate containing a wire filler composed of uniformly spaced stay wires and other wires crossing the same, wire connecting mechanism, guiding means for the gate frame during its movement through the machine, means for imparting an intermittent movement to the carrier for progressively and successively presenting said stay wires and the intersections of the cross wires therewith to said wire connecting mechanism, means for lowering the gate and holding it 115 in such position during the operation of the wire connecting mechanism, and then raising said gate, and guiding means for said wires. 120

33. In a machine of the character described, in combination, a carrier for advancing a gate through the machine, said gate containing a wire filler composed of uniformly spaced stay wires and other wires crossing the same, wire connecting mechanism, guiding means for the gate frame 125 130

- 5 during its movement through the machine, means for imparting an intermittent movement to the carrier for progressively and successively presenting said stay wires and the intersections of the cross wires there-
 10 with to said wire connecting mechanism, means for lowering the gate and holding it in such position during the operation of the wire connecting mechanism and then raising said gate, guiding means for the body of the stay wire operating thereupon during the lowering of the gate, and guiding means for the other wires.
34. In a machine of the character de-
 15 scribed, in combination, a carrier for advanc-
 ing a gate through the machine, said gate containing a wire filler composed of uniformly spaced stay wires and other wires crossing the same, wire connecting mecha-
 20 nism, guiding means yieldingly engaging opposite bars of the gate frame during its movement through the machine and located in alinement with the wire connecting mechanism, means for imparting an intermittent movement to the carrier for progressively and successively presenting said stay wires and the intersections of the cross wires there-
 25 with to said wire connecting mechanism, means for lowering the gate and holding it in such position during the operation of the wire connecting mechanism and then raising said gate, guiding means for the body of the stay wire operating thereupon during the lowering of the gate, and guiding means for the other wires.
35. In a machine of the character de-
 30 scribed, in combination, a carrier for advanc-
 ing a gate through the machine, said gate containing a wire filler composed of uniformly spaced stay wires and other wires crossing the same, wire connecting mecha-
 35 nism, means for imparting an intermittent movement to the carrier for progressively and successively presenting said stay wires and the intersections of the cross wires there-
 40 with to said wire connecting mechanism, and means adapted to engage with the stay wires for squaring the gate frame with respect to the working parts of the machine.
36. In a machine of the character de-
 45 scribed, in combination, a carrier for advanc-
 ing a gate through the machine, said gate containing a wire filler composed of uniformly spaced stay wires and other wires crossing the same, wire connecting mecha-
 50 nism, means for moving the gate sidewise and holding it in such position during the operation of the wire connecting mechanism and then returning said gate to the position from which it was moved, guiding means for the body of the stay wire operating thereupon during the sidewise movement of the gate in one direction, said guiding means comprising a plurality of guiding fingers for alining the stay wires relatively to the wire connecting mechanism, and guiding means for the other wires.
37. In a machine of the character de-
 55 scribed, in combination, a carrier for advanc-
 ing a gate through the machine, said gate containing a wire filler composed of uniformly spaced stay wires and other wires crossing the same, wire connecting mecha-
 60 nism, means for imparting an intermittent movement to the carrier for progressively and successively presenting said stay wires and the intersections of the cross wires there-
 65 with to said wire connecting mechanism, means for lowering the gate and holding it in such position during the operation of the wire connecting mechanism and then raising said gate, guiding means for the body of the stay wire operating thereupon during the lowering of the gate, said guiding means comprising a plurality of guiding fingers adapted to move forwardly and engage and aline the stay wire relatively to the wire connecting mechanism, other guiding means for the stays operating simultaneously with the operation of the wire connecting mechanism, and guiding means for the other wires.
38. In a machine of the character de-
 70 scribed, in combination, a carrier for advanc-
 ing a gate through the machine, said gate containing a wire filler composed of uniformly spaced stay wires and other wires crossing the same, wire connecting mecha-
 75 nism, means for imparting an intermittent movement to the carrier for progressively and successively presenting said stay wires and the intersections of the cross wires there-
 80 with to said wire connecting mechanism, and means adapted to engage with the stay wires for squaring the gate frame with respect to the working parts of the machine.
39. In a machine of the character de-
 85 scribed, in combination, a carrier for advanc-
 ing a gate through the machine, said gate containing a wire filler composed of uniformly spaced stay wires and other wires crossing the same, wire connecting mecha-
 90 nism, means for imparting an intermittent movement to the carrier for progressively and successively presenting said stay wires and the intersections of the cross wires there-
 95 with to said wire connecting mechanism, and means adapted to engage with the stay wires for squaring the gate frame with respect to the working parts of the machine.
40. In a machine of the character de-
 100 scribed, in combination, a carrier for advanc-
 ing a gate through the machine, said gate containing a wire filler composed of uniformly spaced stay wires and other wires crossing the same, wire connecting mecha-
 105 nism, means for imparting an intermittent movement to the carrier for progressively and successively presenting said stay wires and the intersections of the cross wires there-
 110 with to said wire connecting mechanism, and means adapted to engage with the stay wires for squaring the gate frame with respect to the working parts of the machine, other guiding means for alining the stay wires with respect to the wire connecting mechanism, and guiding means for the other wires.
41. In a machine of the character de-
 115 scribed, in combination, wire connecting mechanism, feeding means for advancing a gate through the machine, a shaft for actuating said feeding means, means for operating said shaft to preliminarily advance the gate to operative position in the machine, and other means for intermittently operating said shaft.
42. In a machine of the character de-
 120 scribed, in combination, wire connecting mechanism, feeding means for advancing a gate through the machine, a shaft for actuating said feeding means, means for operating said shaft to preliminarily advance the gate to operative position in the machine, 130

other means for intermittently actuating the feeding means to advance the gate in a step-by-step movement through the machine, and means for reversing the operation of said shaft to return the feeding means to a gate receiving position.

41. In a machine of the character described, in combination, wire connecting mechanism, feeding means for advancing a gate through the machine, a shaft for actuating said feeding means, means for operating said shaft to preliminarily advance the gate to operative position in the machine, other means for intermittently actuating the feeding means to advance the gate in a step-by-step movement through the machine, and means for interrupting the operation of the means for intermittently advancing the gate through the machine, after the completion 20 of the gate.

42. In a machine of the character described, in combination, wire connecting mechanism, means for feeding a gate through the machine, comprising a feeding shaft and 25 chains operated thereby, means for intermittently rotating said shaft for advancing a gate in a step-by-step movement through the machine, and means operated through the movement of said chains for interrupting 30 the rotation of said feeding shaft, after the completion of the gate.

43. In a machine of the character described, in combination, wire connecting mechanism, feeding means for advancing a gate through the machine, means for intermittently operating said feeding means, means operated by said feeding means for interrupting the operation of the means for actuating the feeding means, after the completion 40 of the gate, and means for returning the feeding means to a receiving position.

44. In a machine of the character described, in combination, wire connecting mechanism, feeding means for advancing a gate through the machine, means for intermittently operating said feeding means, means operated by said feeding means for interrupting the operation of the means for actuating the feeding means, after the completion 45 of the gate, means for returning the feeding means to a receiving position, and means operated by the feeding means for interrupting the operation of the means for returning the feeding means to a receiving 50 position, after said feeding means has been returned to a predetermined position.

45. In a machine of the character described, in combination, chains for moving a gate through the machine, a feeding shaft 60 for operating said chains, a timing shaft, means for intermittently rotating the feeding shaft from the timing shaft, means for interrupting the movement of the feeding shaft, after the completion of the gate,

means for reversing the movement of the feeding shaft and with it the movement of the chains, and means for interrupting the operation of the reversing means, when the chains have been moved a predetermined distance.

46. In a machine of the character described, in combination, chains for moving a gate through the machine, a feeding shaft for operating said chains, a timing shaft, means for intermittently rotating the feeding shaft from the timing shaft, means operated by one of the chains for interrupting the movement of the feeding shaft, after the completion of the gate, means for reversing the movement of the feeding shaft and with it the movement of the chains, and means operated by the other of said chains for interrupting the operation of said reversing means, when the chains have been moved a predetermined distance.

47. In a machine of the character described, in combination, chains for moving a gate through the machine, a feeding shaft for operating said chains, a timing shaft, a ratchet wheel and pawl mechanism for rotating the feeding shaft, operating connections between the ratchet wheel and pawl mechanism and the timing shaft, a member on the feeding shaft adapted when moved in one direction to prevent the engagement 95 of the pawl with the ratchet wheel, means operated by one of the chains for moving said member simultaneously with the completion of a gate, whereby the pawl is prevented from engaging the ratchet wheel, 100 and interrupting the movement of the feeding shaft, and means for reversing the movement of the feeding shaft and said chains, to return the chains to receiving position.

48. In a machine of the character described, in combination, chains for moving a gate through the machine, a feeding shaft for operating said chains, a timing shaft, a ratchet wheel and pawl mechanism on said feeding shaft for driving it in one direction, driving connections between said ratchet wheel and pawl mechanism and said timing shaft, means preventing said pawl from engaging the teeth of the ratchet wheel upon the completion of a gate, means operated by one of the chains for actuating said pawl controlling means, and means for reversing the operation of the feeding shaft and with it the chains.

49. In a machine of the character described, in combination, chains for moving a gate through the machine, a feeding shaft for operating said chains, a timing shaft, a ratchet wheel and pawl mechanism on said feeding shaft for driving it in one direction, an eccentric on the timing shaft and driving connections between said ratchet wheel and

pawl mechanism and said eccentric, means preventing said pawl from engaging the teeth of the ratchet wheel upon the completion of the gate, means operated by one of

5 the chains for actuating said pawl controlling means, and means for reversing the operation of the feeding shaft and with it the chains.

50. In a machine of the character described, in combination, chains for moving a gate through the machine, a feeding shaft for operating said chains, a timing shaft, a ratchet wheel and pawl mechanism on said feeding shaft for driving it in one direction, 10 driving connections between said ratchet wheel and pawl mechanism and said timing shaft, means preventing said pawl from engaging the teeth of the ratchet wheel upon the completion of the gate, means operated 15 by one of the chains for actuating said pawl controlling means, means for reversing the operation of the feeding shaft and with it the chains, and means operated by the other of said chains for interrupting the movement 20 of said reversing means.

51. In a machine of the character described, in combination, chains for moving a gate through the machine, a feeding shaft for operating said chains, a timing shaft, a 30 ratchet wheel and pawl mechanism on said feeding shaft for driving it in one direction, driving connections between said ratchet wheel and pawl mechanism and said timing shaft, means preventing said pawl 35 from engaging the teeth of the ratchet wheel upon the completion of the gate, means operated by one of the chains for actuating said pawl controlling means, means for reversing the operation of the feeding shaft and 40 with it the chains, means operated by the other of said chains for interrupting the movement of said reversing means, and means for releasing the pawl controlling means to permit said pawl to again engage 45 the teeth of the ratchet wheel.

52. In a machine of the character described, in combination, chains for moving a gate through the machine, a feeding shaft for operating said chains, means for rotating 50 said feeding shaft to preliminarily advance a gate to operative position in the machine, a timing shaft, a ratchet wheel and pawl mechanism on said feeding shaft for driving it in one direction, driving connections between said ratchet wheel and pawl mechanism and said timing shaft, means preventing said pawl from engaging the teeth of the ratchet wheel upon the completion 55 of the gate, means operated by one of the chains for actuating said pawl controlling means, said pawl controlling means being operated at a time previous to the completion of a full stroke of the pawl, means for reversing the operation of the feeding

65 shaft, and with it the chains, and means for releasing the pawl controlling means to permit said pawl to again engage the teeth of the ratchet wheel.

53. In a machine of the character described, in combination, chains for moving a gate through the machine, a feeding shaft for operating said chains, a timing shaft, a ratchet wheel and pawl mechanism on said feeding shaft for driving it in one direction, driving connections between said ratchet 70 wheel and pawl mechanism and said timing shaft, a member on said feeding shaft adapted when moved in one direction to present a surface over which the pawl will ride and prevent its engagement with the teeth of the 75 ratchet wheel, means for locking said member in operative position when moved, means operated by one of the chains for moving said member to operative position, and means for releasing the locking means from 80 the member, whereby the member may move and permit said pawl to again engage the teeth on the ratchet wheel.

54. In a machine of the character described, in combination, chains for moving a 90 gate through the machine, a feeding shaft for operating said chains, a timing shaft, a ratchet wheel and pawl mechanism on said feeding shaft for driving it in one direction, driving connections between said ratchet 95 wheel and pawl mechanism and said timing shaft, a member on said feeding shaft adapted when moved in one direction to present a surface over which the pawl will ride and prevent its engagement with the teeth of the 100 ratchet wheel, the disengagement of the pawl from the ratchet wheel occurring at a time previous to the completion of a full stroke of the pawl, means for locking said member in operative position when moved, 105 means operated by one of the chains for moving said member to operative position, and means for releasing the locking means from the member, whereby the member may move and permit said pawl to engage the 110 teeth on the ratchet wheel, the reengagement of said pawl with the ratchet wheel occurring with the tooth last previously engaged.

55. In a machine of the character described, in combination, chains for moving a gate through the machine, a feeding shaft for operating said chains, a timing shaft, a ratchet wheel and pawl mechanism on said feeding shaft for driving it in one direction, driving connections between said ratchet 115 wheel and pawl mechanism and said timing shaft, a member on said feeding shaft adapted when moved in one direction to present a surface over which the pawl will ride and prevent its engagement with the teeth of the 120 ratchet wheel, a lever and connections between said lever and said member, means connected with the chains for operating said

lever to move the member to operative position, means for locking said member when in operative position, means for releasing the locking means from said member, and 5 means for returning the member to its initial position.

56. In a machine of the character described, in combination, chains for moving a gate through the machine, a feeding shaft 10 for operating said chains, a timing shaft, a ratchet wheel and pawl mechanism on said feeding shaft for driving it in one direction, driving connections between said ratchet wheel and pawl mechanism and said 15 timing shaft, a member on said feeding shaft adapted to move in one direction to present a surface over which the pawl will ride and prevent its engagement with the teeth of the ratchet wheel, a lever and connections between said lever and said member, means connected with the chains for operating said lever to move the member to operative position, means for locking said member when in operative position, means 20 for reversing the movement of the feeding shaft and with it the chains, means operated by the chains for interrupting the movement of the reversing means, means for releasing said member locking means, and means for 25 returning the member to its initial position.

57. In a machine of the character described, in combination, chains for moving a gate through the machine, a feeding shaft for operating said chains, a timing shaft, a 30 ratchet wheel fixed on the feeding shaft, a pawl movable about the feeding shaft and adapted to engage with the teeth of the ratchet wheel, operating connections between said pawl and said timing shaft, a 35 member loosely carried on said feeding shaft and adapted when moved in one direction to present a surface over which the pawl will ride and prevent its engagement with the teeth of the ratchet wheel, means for yieldingly holding said member in inoperative 40 position, means for locking said member in operative position when moved, means operated by said chains for moving said member to operative position, and means for releasing 45 the locking means from the member, whereby the member may move and permit said pawl to again engage the teeth of the ratchet wheel.

58. In a machine of the character described, in combination, chains for moving a gate through the machine, a feeding shaft 55 for operating said chains, a timing shaft, a ratchet wheel fixed on the feeding shaft, a pawl movable about the feeding shaft adapted to engage the teeth of the ratchet wheel, operating connections between said pawl and said timing shaft, a member loosely carried on said feeding shaft adapted to be moved in one direction to present 60 a surface over which the pawl will ride and

prevent its engagement with the teeth of the ratchet wheel, means for yieldingly holding said member in inoperative position, a lever and connections between said lever and said member, means carried by 70 one of the chains and adapted to engage said lever and by such engagement move the member to operative position, means for locking said member when in operative position, and means for releasing the locking 75 means from said member, whereby the member may move and permit said pawl to again engage the teeth of the ratchet wheel.

59. In a machine of the character described, in combination, chains for moving a gate through the machine, a feeding shaft 80 for operating said chains, a timing shaft, a ratchet wheel fixed on the feeding shaft, a pawl movable about the feeding shaft adapted to be moved in one direction to present a surface over which the pawl will ride and prevent 85 its engagement with the teeth of the ratchet wheel, said member provided with a notch, means for yieldingly holding said member in inoperative position, a lever and connections between said lever and said member, means carried by one of the chains and adapted to engage said lever and by such engagement move the member to operative 90 position, a bar adapted to be yieldingly forced into the notch in said member when the member has been moved to operative position, and a lever for releasing said bar from the notch in the member, whereby the member may move and permit said pawl to again engage the teeth of the ratchet wheel. 95

60. In a machine of the character described, in combination, chains for moving a gate through the machine, a feeding shaft for operating said chains, a timing shaft, a ratchet wheel fixed on the feeding shaft, a 100 pawl movable about the feeding shaft adapted to engage the teeth of the ratchet wheel, operating connections between said pawl and said timing shaft, a member loosely carried on said feeding shaft adapted to be moved in one direction to present a surface over which the pawl will ride and prevent 105 its engagement with the teeth of the ratchet wheel, said member provided with a notch, means for yieldingly holding said member in inoperative position, a lever and connections between said lever and said member, means carried by one of the chains and adapted to engage said lever and by such engagement move the member to operative 110 position, a bar adapted to be yieldingly forced into the notch in said member when the member has been moved to operative position, means for reversing 115 the operation of said feeding shaft and 120 125 130

with it the chains, means operated by the other of said chains for interrupting the movement of said reversing means, and a lever for releasing the said bar from the 5 notch in the member, whereby the member may move and permit said pawl to engage the teeth of the ratchet wheel.

61. In a machine of the character described, in combination, chains for moving 10 a gate through the machine, a feeding shaft for operating said chains, a timing shaft, means for rotating the feeding shaft to preliminarily advance the chains with a gate to an operative position in the machine, a 15 ratchet wheel and pawl mechanism on said feeding shaft for intermittently moving a gate through the machine after it has been advanced to preliminary position, driving connections between said ratchet wheel and 20 pawl mechanism and said timing shaft, a member on said feeding shaft adapted when moved in one direction to present a surface over which the pawl will ride and prevent its engagement with the teeth of the ratchet 25 wheel, the disengagement of the pawl from the ratchet wheel occurring at a time previous to the completion of a full stroke of the pawl, means for locking said member in operative position when moved, means 30 operated by the chains for moving said member to operative position, means for reversing the movement of the feeding shaft and with it the chains to return the chains to a gate receiving position, and means for 35 releasing the locking means from said member, whereby the member may move and permit said pawl to engage the teeth on the ratchet wheel, the reengagement of said pawl with the ratchet wheel occurring with 40 the tooth last previously engaged.

62. A machine for connecting the intersections of the filler wires of a gate frame, including wire connecting mechanism, means for feeding tire-wire stock to said wire connecting mechanism, means for moving a gate through the machine to present the intersections of said wires to said wire connecting mechanism, means for arresting the movement of the gate when the intersections 45 of the wires are brought coincident with the wire connecting mechanism, and means for operating said wire connecting mechanism during this pause in the movement of the gate through the machine, the operation of 50 the wire connecting mechanism severing the tire-wire stock and connecting the severed sections thereof to the intersections of the wires in the gate.

63. A machine for connecting the intersections of the filler wires of a gate frame, including wire connecting mechanism, means for feeding tire-wire stock to said wire connecting mechanism, means for moving a gate through the machine to present the intersections 55 of said wires to said wire connecting

mechanism, means for arresting the movement of the gate when the intersections of the wires are brought coincident with the wire connecting mechanism, means for moving the gate laterally, means for alining the 70 stay wire during the lateral movement of the gate, and means for operating said wire connecting mechanism during the pause in the movement of the gate through the machine, the operation of the wire connecting 75 mechanism severing the tie-wire stock and connecting the severed sections thereof to the intersections of the wires in the gate.

64. A machine for connecting the intersections of the filler wires of a gate frame, 80 including a row of spaced wire connecting mechanisms, means for feeding tie-wire stock to each of said wire connecting mechanisms, means for moving a gate through the machine to present the intersections of said 85 wires to said wire connecting mechanisms, means for arresting the movement of the gate when the intersections of the wires are brought coincident with said wire connecting mechanisms, and means for simultaneously operating said wire connecting mechanisms during this pause in the movement of the gate through the machine, the operation of each of said wire connecting mechanisms 90 severing a section of wire from the tie-wire 95 stock fed thereto, and connecting said severed sections to the intersections of the wires in the gate.

65. A machine for connecting the intersections of the filler wires of a gate frame, 100 including a row of spaced wire connecting mechanisms, each set of wire connecting mechanisms comprising a fixed member, and cutting, forming and driving parts, the cutting, forming, and driving parts of such 105 mechanism being located on one side of the path of movement of the gate through the machine, means for feeding tie-wire stock to each of said wire connecting mechanisms, means for moving a gate through the machine to present the intersections of said 110 wires to said wire connecting mechanisms, means for arresting the movement of the gate when the intersections of the wires are brought coincident with said wire connecting mechanisms, and means for simultaneously operating said wire connecting mechanisms during this pause in the movement of the gate through the machine, the operation of each of said wire connecting mechanisms 115 severing a section from the tie-wire stock, forming it into a staple-like member and driving said staple-like member across the intersections of the wires in the gate.

66. A machine for connecting the intersections of the filler wires of a gate frame, 120 including a row of spaced wire connecting mechanisms, each set of wire connecting mechanisms comprising a fixed member, and cutting, forming and driving parts, the cut- 125

ting, forming and driving parts of such mechanism being located on one side of the path of movement of the gate through the machine, means for feeding tie-wire stock to 5 each of said wire connecting mechanisms, means for moving a gate through the machine to present the intersections of said wires to said wire connecting mechanisms, means for arresting the movement of the 10 gate when the intersections of the wires are brought coincident with said wire connecting mechanisms, means for moving the gate laterally in the direction of the fixed members of said wire connecting mechanism, means 15 for alining the stay wire during the lateral movement of the gate, and means for simultaneously operating said wire connecting mechanisms during the pause in the movement of the gate through the machine, the 20 operation of each of said wire connecting mechanisms severing a section from the tie-wire stock, forming it into a staple-like member and driving said staple-like member across the intersections of the wires in 25 the gate.

67. A machine for connecting the intersections of the filler wires of a gate frame including a row of spaced wire connecting mechanisms, each set of wire connecting mechanisms comprising a fixed member, and cutting, forming and driving parts, the cutting, forming and driving parts of such mechanism being located on one side of the path of movement of the gate through the machine, means for 30 feeding tie-wire stock to each of said wire connecting mechanisms, guiding means for the gate frame adapted to frictionally engage said frame, means for moving a gate through the machine to present the intersections 35 of said wires to said wire connecting mechanisms, means for arresting the movement of the gate when the intersections of the wires are brought coincident with said wire connecting mechanisms, means for moving the gate laterally in the direction of 40 the fixed members of said wire connecting mechanisms, means for alining the stay wire crosswise of the wire connecting mechanisms during the lateral movement of the gate, 45 guiding means for the other wires, and means for simultaneously operating said wire connecting mechanisms during the pause in the movement of the gate through the machine, the operation of each of said 50 wire connecting mechanisms severing a section from the tie-wire stock, forming it into a staple-like member, and driving said staple-like member across the intersections of the wires in the gate.

68. A machine for connecting the intersections of the filler wires of a gate frame, including a row of spaced wire connecting mechanisms, means for feeding tie-wire stock to each of said wire connecting mechanisms, 65 means for moving a gate through the ma-

chine to present the intersections of said wires to said wire connecting mechanisms, means for arresting the movement of the gate when the intersections of the wires are brought coincident with said wire connecting 70 mechanisms, means for moving the gate laterally, means for alining the stay wire crosswise of the wire connecting mechanisms during the lateral movement of the gate, such alining means comprising a plurality of wire 75 guiding fingers, and means for moving said wire connecting mechanism during the pause in the movement of the gate through the machine, the operation of each of said wire connecting mechanisms severing a section of wire from the tie-wire stock fed thereto, and connecting said severed sections to the intersections of the wires in the gate. 80

69. A machine for connecting the intersections of the filler wires of a gate frame, 85 including a row of spaced wire connecting mechanisms, means for feeding tie-wire stock to each of said wire connecting mechanisms, guiding means for the gate frame adapted to frictionally engage said frame, said guiding means being so located as to fix the position of the first of the series of intersections of the wires with respect to the position of the first set of wire connecting mechanisms in the row, and thereby spacing the other of 90 said intersections with respect to the remaining sets of wire connecting mechanisms, means for moving a gate through the machine to present the intersections of said wires to said wire connecting mechanisms, means for arresting the movement of the gate when the intersections of the wires are brought coincident with said wire connecting mechanisms, and means for simultaneously operating said wire connecting mechanisms during this pause in the movement of the gate through the machine, the operation of each of said wire connecting mechanisms severing a section of wire from the tie-wire stock fed 95 thereto, and connecting said severed sections to the intersections of the wires in the gate. 100

70. A machine for connecting the intersections of the filler wires of a gate frame, including a row of spaced wire connecting mechanisms, means for feeding tie-wire stock to each of said wire connecting mechanisms, guiding means for the gate frame adapted to frictionally engage said frame upon opposite sides thereof, one of such guiding means comprising an adjustably 115 supported grooved roller, the other of such guiding means comprising a pair of co-acting members having a yielding relation with respect to each other and being so located as to fix the position of the first of the 120 series of intersections of the wires with respect to the position of the first set of wire connecting mechanisms in the row and thereby spacing the other of said intersections with respect to the remaining sets of wire 125 connecting mechanisms. 130

- connecting mechanisms, means for moving a gate through the machine to present the intersections of said wires to said wire connecting mechanisms, means for arresting the movement of the gate when the intersections of the wires are brought coincident with said wire connecting mechanisms, and means for simultaneously operating said wire connecting mechanisms during this pause in the movement of the gate through the machine, the operation of each of said wire connecting mechanisms severing a section of wire from the tie-wire stock fed thereto, and connecting said severed sections to the intersections of the wires in the gate.
71. A machine for connecting the intersections of the filler wires of a gate frame, including wire connecting mechanism, means for feeding tie-wire stock to said wire connecting mechanism, means for moving a gate through the machine to present the intersections of said wires to said wire connecting mechanism, supporting means for sustaining the weight of the gate, means for lowering and raising said supporting means, guiding means for the gate connected with said lowering and raising means, whereby the guiding and supporting means may be lowered and raised in unison, means for arresting the movement of the gate when the intersections of the wires are brought coincident with the wire connecting mechanism, and means for operating said wire connecting mechanism during this pause in the movement of the gate through the machine, the operation of the wire connecting mechanism severing the tie-wire stock and connecting the severed sections thereof to the intersections of the wires in the gate.
72. A machine for connecting the intersections of the filler wires of a gate frame, including wire connecting mechanism, means for feeding tie-wire stock to said wire connecting mechanism, means for moving a gate through the machine to present the intersections of said wires to said wire connecting mechanism, supporting means for sustaining the weight of the gate, means for lowering and raising said supporting means, guiding means for the gate, means for aligning the stay wire crosswise of the wire connecting mechanism during the lowering of the gate supporting means, the guiding means for the gate and the means for aligning the stay wire being connected with the gate lowering and raising means, whereby they may be moved in unison, means for arresting the movement of the gate when the intersections of the wires are brought coincident with the wire connecting mechanism, and means for operating said wire connecting mechanism during this pause in the movement of the gate through the machine, the operation of the wire connecting mechanism severing the tie-wire stock and connecting the severed sections thereof to the intersections of the wires in the gate.
73. A machine for connecting the intersections of the filler wires of a gate frame, including a row of spaced wire connecting mechanisms, each set of wire connecting mechanisms comprising a fixed member, and movable cutting, forming and driving parts, said movable parts of the wire connecting mechanism being located on one side of the path of movement of the gate through the machine, means for operating the cutting and forming parts of said wire connecting mechanisms, and other means for operating the driving parts, means for moving a gate through the machine to present the intersections of said wires to said wire connecting mechanisms, and means for arresting the movement of the gate when the intersections of the wires are brought coincident with said wire connecting mechanisms.
74. A machine for connecting the intersections of the filler wires of a gate frame, including a row of spaced wire connecting mechanisms, each set of wire connecting mechanisms comprising a fixed member, and movable cutting, forming and driving parts, said movable parts of the wire connecting mechanisms being located on one side of the path of movement of the gate through the machine, a timing shaft, means for operating the cutting and forming parts of said wire connecting mechanisms from said timing shaft, and other means for operating said driving parts from said timing shaft, means for moving a gate through the machine to present the intersections of said wires to said wire connecting mechanisms, and means for arresting the movement of the gate when the intersections of the wires are brought coincident with said wire connecting mechanisms.
75. A machine for connecting the intersections of the filler wires of a gate frame, including a row of spaced wire connecting mechanisms, each set of wire connecting mechanisms comprising a fixed member, and movable cutting, forming and driving parts, said movable parts of the wire connecting mechanisms being located on one side of the path of movement of the gate through the machine, a timing shaft, means for operating the cutting and forming parts of said wire connecting mechanisms from said timing shaft, and other means for operating said driving parts from said timing shaft, the connections between the timing shaft and the cutting and forming parts and between the timing shaft and the driving parts of said wire connecting mechanisms being so timed in their movements relatively to each other that the cutting and forming parts are operated slightly in advance of the operation of said driving parts, means for moving the gate through the machine to

present the intersections of said wires to said wire connecting mechanisms, and means for arresting the movement of the gate when the intersections of the wires are brought 5 coincident with said wire connecting mechanisms.

76. A machine for connecting the intersections of the filler wires of a gate frame, including a row of spaced wire connecting 10 mechanisms, each set of wire connecting mechanisms comprising a fixed member, and movable cutting, forming and driving parts, said movable parts of the wire connecting mechanisms being located on one side of the 15 path of movement of the gate through the machine, means for feeding tie-wire stock to each of said wire connecting mechanisms, a timing shaft, means for operating the cutting and forming parts of said wire connecting mechanisms from said timing shaft, and other means for operating said driving parts from said timing shaft, the connections between the timing shaft and the cutting and forming parts, and between the 20 timing shaft and the driving parts of said wire connecting mechanisms being so timed in their movements relatively to each other that the cutting and forming parts are operated slightly in advance of the operation 25 of said driving parts, whereby tie-wire sections may be severed from the tie-wire stock and formed into staple-like members to be engaged and driven across the intersections of the filler wires by said driving parts, 30 means for moving the gate through the machine to present the intersections of said wires to said wire connecting mechanisms, and means for arresting the movement of the gate when the intersections of the wires 35 40 are brought coincident with said wire connecting mechanisms.

77. In a machine of the character described in combination, means for intermittently feeding a gate through the machine, 45 said gate having connected thereto uniformly spaced stay wires and other wires crossing the same, wire connecting mechanisms comprising a series of sets of stationary die-members, and movable cutting, 50 forming and driving parts, means for operating said cutting and forming parts, and other means for operating said driving parts of said wire connecting mechanisms.

78. In a machine of the character described, in combination, means for intermittently feeding a gate through the machine, 55 said gate having connected thereto uniformly spaced stay wires and other wires crossing the same, wire connecting mechanisms, means for feeding tie-wire stock to said wire connecting mechanisms, and means for operating said wire connecting mechanisms to sever from said tie-wire stock, tie-wire sections, form said sections into staple-

like members and drive said staple-like 65 members across the intersections of the stay wires and other wires crossing the same.

79. In a machine of the character described, in combination, means for intermittently feeding a gate through the machine, 70 said gate having connected thereto uniformly spaced stay wires and other wires crossing the same, wire connecting mechanisms, means for feeding tie-wire stock to said wire connecting mechanisms, and means for operating said wire connecting mechanisms to sever from said tie-wire stock, tie-wire sections, which said sections are united about said stay wires and other wires where they cross the same. 80

80. In a machine of the character described, in combination, means for intermittently feeding a gate through the machine, said gate having connected thereto uniformly spaced stay wires and other wires 85 crossing the same, a row of spaced wire connecting mechanisms, each set of wire connecting mechanisms including wire cutting, forming and driving parts, means for feeding tie-wire stock to each of said wire connecting mechanisms, means for operating said cutting and forming parts to sever tie-wire sections from the tie-wire stock and 90 form said sections into staple-like members, and means for operating said driving parts of said wire connecting mechanisms to engage the arcuate portions of said staple-like members and drive the same diagonally across the intersections of the stay wires, 95 where the other wires cross the same, whereby the ends of said staple-like members will unite said stays and cross wires. 100

81. In a machine of the character described, in combination, means for intermittently feeding a gate through the machine, 105 said gate having connected thereto uniformly spaced stay wires and other wires crossing the same, wire connecting mechanisms, comprising a series of sets of stationary die-members, and movable cutting, forming and driving parts, said movable cutting, forming and driving parts being located on one side of the path of movement of the gate through the machine, means for feeding tie-wire stock to said wire connecting mechanisms, means for operating said cutting and forming parts to move the same in the direction of said die-members and during such movement sever tie-wire sections from said tie-wire stock and form the same into staple-like members, and other means for operating said driving parts of said wire connecting mechanisms to also move the same in the direction of said die-members and during such movement engage said staple-like members and force the same across the stay wires and other wires where they intersect, and 115 into engagement with said die-members. 120 125

whereby the ends of the staple-like members may be forced about the intersections of said wires.

82. In a machine of the character described, in combination, means for intermittently feeding a gate through the machine, said gate having connected thereto uniformly spaced stay wires and other wires crossing the same, wire connecting mechanisms, comprising a series of sets of stationary die-members, and movable cutting, forming and driving parts, said movable cutting, forming and driving parts being located on one side of the path of movement of the gate through the machine, means for feeding tie-wire stock to said wire connecting mechanisms, a timing shaft, operating connections between said timing shaft and said forming parts to simultaneously move the same in the direction of said die-members and during such movement sever tie-wire sections from said tie-wire stock and form the same into staple-like members, other operating connections between said timing shaft and said driving parts of said wire connecting mechanisms to also move the same in the direction of said die-members and during such movement engage said staple-like members and force the same across the stay wires and other wires where they intersect, and into engagement with said die-members whereby the ends of the staple-like members may be forced about the intersections of said wires.
83. In a machine of the character described, in combination, means for intermittently feeding a gate through the machine, said gate having connected thereto uniformly spaced stay wires and other wires crossing the same, wire connecting mechanisms, comprising a series of sets of stationary die-members and movable cutting, forming and driving parts, said cutting and forming parts including hollow blocks through which the driving parts of said wire connecting mechanisms move, wire forming anvils associated with said hollow blocks, a reciprocally supported member to which are connected said hollow blocks, an additional reciprocally supported member to which are connected the driving parts of said wire connecting mechanisms, a timing shaft, and connections between said timing shaft and said reciprocally supported members.
84. In a machine of the character described, in combination, means for intermittently feeding a gate through the machine, said gate having connected thereto uniformly spaced stay wires and other wires crossing the same, wire connecting mechanisms, comprising a series of sets of stationary die-members and movable cutting, forming and driving parts, said cutting and forming parts including hollow parts
- through which the driving parts of said wire connecting mechanisms move, wire forming anvils associated with said hollow blocks and movable therein, a reciprocally supported member to which are connected said hollow blocks, an additional reciprocally supported member to which are connected the driving parts of said wire connecting mechanisms, a timing shaft, connections between said timing shaft and said reciprocally supported members, means for feeding tie-wire stock to said wire connecting mechanisms, the relation of said reciprocally supported members being such that when said timing shaft is operated said cutting and forming parts will sever sections of wire from the tie-wire stock, form the same into staple-like members over said anvils in advance of the movement of said driving parts, the driving parts operated to engage the formed staple-like members and in driving the same forwardly move said anvils, the staple-like members being driven across the intersections of the stays and other wires and against said die-members.
85. In a machine of the character described, in combination, means for intermittently feeding a gate through the machine, wire connecting mechanisms comprising a series of sets of spaced stationary die-members, and movably supported thereabove wire cutting and forming parts, and a driving part, said forming parts including a hollow block through which said driving parts move, and associated wire forming anvils, means for simultaneously moving said forming blocks toward said die-members, and means for simultaneously moving said driving parts, the timing of the forming and driving parts of said wire connecting mechanisms being such that the forming parts have movement imparted thereto slightly in advance of said driving parts.
86. In a machine of the character described, in combination, a plurality of stationary die-members, and a plurality of wire cutting, forming and driving parts movably supported above said die-members, a timing shaft, a reciprocally supported member and connections between said member and the cutting and forming parts, an additional reciprocally supported member, and connections between said last mentioned member and said driving parts of the wire connecting mechanisms, and operating connections between both of said reciprocally supported members and said timing shaft.
87. In a machine of the character described, in combination, a plurality of stationary die-members, a plurality of hollow wire cutting and forming blocks movably supported above said die-members, a driving part reciprocally carried in each of said hollow blocks, a wire forming anvil asso-

- ciated with each hollow block and movable therein, a timing shaft, a reciprocally supported member and connections between said member and said hollow blocks, an 5 additional reciprocally supported member and connections between said last mentioned member and said driving parts, eccentrics carried on said timing shaft, and operating connections between said eccentrics and both 10 of said reciprocally supported members.
88. In a machine of the character described, in combination, a plurality of stationary die-members, a plurality of hollow wire-cutting and forming blocks movably 15 supported above said die-members, a driving part reciprocally carried in each of said hollow blocks, a wire forming anvil associated with each hollow block and movable therein, means for feeding tie-wire stock 20 across the lower ends of said hollow blocks when the same are in an elevated position, and also across the ends of said anvils, a timing shaft, a reciprocally supported member and connections between said member 25 and said hollow blocks, eccentrics on the timing shaft and connections between said eccentrics and said reciprocally supported member, whereby said hollow blocks may be moved toward said die-members and during 30 such movement sever sections of wire from the tie-wire stock and form the same into staple-like members across said anvils, an additional reciprocally supported member and connections between said last mentioned member and said driving parts, other eccentrics on the timing shaft, and operating 35 connections between said eccentrics and said additional reciprocally supported member, whereby when said last mentioned member is moved the driving parts will engage 40 with and drive said staple-like members, and during such movement move the anvils to release the same from said staple-like members.
- 45 89. In a machine of the character described, in combination, a timing shaft, a pair of reciprocally supported members, connections between said timing shaft and one of said members and other connections between 50 said timing shaft and the other of said members, a plurality of hollow blocks connected with one of said reciprocally supported members, a wire forming anvil associated with each block and movable therein, means for pivoting 55 supporting said anvil, a driving part movable through each block and adapted to engage with the anvil associated therewith to move it out of the way during the continued movement of the driving parts, said driving parts connected to move with the other of said reciprocally supported members, a stationary die-member positioned 60 approximately at the end of the stroke of said hollow blocks and driving parts, and adapted to cooperate therewith, wire guiding means associated with each of said die-members, and yieldingly held in operative position, and other wire guiding means movably supported to be moved toward and from said die-members.
- 65 90. In a machine of the character described, in combination, a timing shaft, a pair of reciprocally supported members, connections between said timing shaft and one of said members, and other connections between 70 said timing shaft and the other of said members, a plurality of hollow blocks connected with one of said reciprocally supported members, wire cutting means on each block and wire guiding means also on each block, a wire forming anvil associated with each block and movable therein, means for pivoting 75 supporting said anvil, a driving part movable through each block and adapted to engage with the anvil associated therewith to move it out of the way during the continued movement of the driving parts, said driving parts connected to move with the other of said reciprocally supported members, a stationary die-member positioned approximately at the end of the stroke of said hollow blocks and driving parts, and adapted to cooperate therewith, wire guiding means associated with each of said die-members, and yieldingly held in operative position, and other wire guiding means movably supported to be moved toward and from said die-members.
- 80 91. In a machine of the character described, in combination, a timing shaft, a pair of reciprocally supported members, connections between said timing shaft and one of said members, and other connections between 85 said timing shaft and the other of said members, a plurality of hollow blocks connected with one of said reciprocally supported members, wire cutting means on each block and wire guiding means also on each block, a wire forming anvil associated with each block and movable therein, means for pivoting 90 supporting said anvil, a driving part movable through each block and adapted to engage with the anvil associated therewith to move it out of the way during the continued movement of the driving parts, said driving parts connected to move with the other of said reciprocally supported members, a stationary die-member positioned approximately at the end of the stroke of said hollow blocks and driving parts, and adapted to cooperate therewith, wire guiding means associated with each of said die-members, and yieldingly held in operative position, and other wire guiding means movably supported to be moved toward and from said die-members.
- 95 92. In a machine of the character described, in combination, means for intermittently moving a gate through the machine, said gate having connected thereto uniformly spaced stay wires and other wires crossing the same, a timing shaft, a pair of reciprocally supported members, connections between said timing shaft and one of said members, and other connections between 100 said members, and yieldingly held in operative position, and other wire guiding means movably supported to be moved toward and from said die-members.
- 105 110 115 120 125

said timing shaft and the other of said members, a plurality of hollow blocks connected with one of said reciprocally supported members, a wire forming anvil associated with each block and movable therein,

- means for pivotally supporting said anvil, a driving part movable through the block and adapted to engage with the anvil associated therewith to move it out of the way 5
10 during the continued movement of the driving part, said driving parts connected to move with the other of said reciprocally supported members, means for feeding tie-wire stock to be operated upon by said hollow blocks and driving parts, a stationary die-member positioned approximately at the end of the stroke of said hollow block and driving parts, and adapted to coöperate therewith, positng mechanism for said gate 15
20 and the wires thereto attached, and means movable with said positng mechanism for positioning the stay wires relatively to said die-members.

93. In a machine of the character described, in combination, means for intermittently moving a gate through the machine, said gate having connected thereto uniformly spaced stay wires and other wires crossing the same, wire connecting mechanisms including sets of stationary die-members and movably supported cutting, forming and driving parts, said die-members being located on one side of the path of movement of the gate, and the movably supported parts of said wire connecting mechanisms being located on the other side of the path of movement of the gate, means for operating said movable parts of the wire connecting mechanisms, a positng mechanism 30 for the gate and the wires thereto attached, and means movable with said positng mechanism for positioning the stay wires relatively to said die-members.

94. In a machine of the character described, in combination, means for intermittently moving a gate through the machine, said gate having connected thereto uniformly spaced stay wires and other wires crossing the same, wire connecting mechanisms including sets of stationary die-members and movably supported cutting, forming and driving parts, said die-members being located on one side of the path of movement of the gate, and the movably supported parts of said wire connecting mechanisms being located on the other side of the path of movement of the gate, means for operating said movable parts of the wire connecting mechanisms, means adapted to 40 engage with the stay wires for squaring the gate relatively to the operative parts of the machine, a positng mechanism for the gate and the wires thereto attached, means movable with said positng mechanism for posi-

tioning the stay wires relatively to said die-members, and wire guiding means associated with said wire connecting mechanisms.

95. In a machine of the character described, in combination, means for intermittently moving a gate through the machine, said gate having connected thereto uniformly spaced stay wires and other wires crossing the same, guiding means for the gate, other means for engaging the stay wires to square the gate with respect to the operative parts of the machine, wire connecting mechanisms including sets of stationary die-members and movably supported cutting, forming and driving parts, said die-members being located on one side of the path of movement of the gate, and the movably supported parts of said wire connecting mechanisms being located on the other side of the path of movement of the gate, means for operating said movable parts of the wire connecting mechanisms, means for feeding tie-wire stock to said wire connecting mechanisms, a positng mechanism for the gate and the wires thereto attached, and means movable with said positng mechanism for positioning the stay wires relatively to said die-members.

96. In a machine of the character described, in combination, wire connecting mechanism including a plurality of vertically movable parts and stationary parts located therebeneath, means for intermittently moving a gate through the machine and between the movable and stationary parts of said wire connecting mechanism, said gate having connected thereto uniformly spaced stay wires and other wires crossing the same, means for lowering and raising the movable parts of said wire connecting mechanism, means for feeding tie-wire stock to said wire connecting mechanism, said tie-wire stock feeding means operating during the interval of time when the movable parts of the wire connecting mechanism have been raised and just preceding the movement of lowering the same, means for arresting the movement of the gate when the intersections of the stay wires and cross wires therewith are brought coincident with the wire connecting mechanism, a positng mechanism for the gate and the wires thereto attached, and means movable with said positng mechanism for positioning the stay wires relatively to said die-members.

97. In a machine of the character described, in combination, wire connecting mechanism, means for intermittently operating said wire connecting mechanism, means for intermittently moving a gate through the machine to present the intersections of crossed wires therein to said wire connecting mechanism, means for feeding tie-wire

stock to said wire connecting mechanism, said tie-wire stock feeding means operating during the interval of time between each operation of said wire connecting mechanism, and means for arresting the movement of the gate when the intersections of said wires are brought coincident with said wire connecting mechanism.

98. In a machine of the character described, in combination, wire connecting mechanism, means for intermittently operating said wire connecting mechanism, means for intermittently moving a gate through the machine to present the intersections of the crossed wires therein to said wire connecting mechanism, means for arresting the movement of the gate when the intersections of said wires are brought coincident with said wire connecting mechanism, a positng mechanism for the gate and the wires thereto attached, said positng mechanism operating during the pause in the movement of the gate through the machine, and means for feeding tie-wire stock to said wire connecting mechanism, said tie-wire stock feeding means operating during the interval of time between such operation of said wire connecting mechanism.

99. In a machine of the character described, in combination, wire connecting mechanism, means for intermittently operating said wire connecting mechanism, means for intermittently moving a gate through the machine to present the intersections of the crossed wires therein to said wire connecting mechanism, means for arresting the movement of the gate when the intersections of said wires are brought coincident with said wire connecting mechanism, a positng mechanism for the gate and the wires thereto attached, said positng mechanism operating during the pause in the movement of the gate through the machine, means movable with the said positng mechanism for positioning certain of the wires in the gate relatively to said wire connecting mechanism, and means for feeding tie-wire stock to said wire connecting mechanism, said tie-wire stock feeding means operating during the interval of time between each operation of said wire connecting mechanism.

100. In a machine of the character described, in combination, wire connecting mechanism, means for intermittently operating said wire connecting mechanism, a carrier for advancing a gate through the machine to present the intersections of crossed wires therein to said wire connecting mechanism, means for imparting movement to the carrier to preliminarily advance the gate to operative position in the machine, other means for intermittently operating said carrier, means for arresting the movement of the carrier when the intersections of the wires in said gate are brought coincident with said wire connecting mechanism.

101. In a machine of the character described, in combination, wire connecting mechanism, means for intermittently operating said wire connecting mechanism, a carrier for advancing a gate through the machine to present the intersections of crossed wires therein to said wire connecting mechanism, means for imparting movement to the carrier to preliminarily advance the gate to operative position in the machine, other means for intermittently operating said carrier, means for arresting the movement of the carrier when the intersections of the wires in said gate are brought coincident with said wire connecting mechanism.

102. In a machine of the character described, in combination, wire connecting mechanism, means for intermittently operating said wire connecting mechanism, a carrier for advancing a gate through the machine to present the intersections of the crossed wires therein to said wire connecting mechanism, means for imparting movement to the carrier to preliminarily advance the gate to operative position in the machine, other means for intermittently operating said carrier, means for arresting the movement of the carrier when the intersections of the wires in said gate are brought coincident with said wire connecting mechanism, a positng mechanism for the gate and the wires thereto attached, said positng mechanism operating during the pause in the movement of the gate through the machine, and means for feeding tie-wire stock to said wire connecting mechanism, said tie-wire stock feeding means operating during the interval of time between each operation of said wire connecting mechanism.

103. In a machine of the character described, in combination, means for intermittently moving a gate through the machine, supporting members for said gate, and means for lowering and raising said supporting members, said lowering and raising means having a predetermined move-

ment relative to the movement of the gate through the machine.

104. In a machine of the character described, in combination, means for moving a gate through the machine, means for arresting the movement of the gate at a predetermined point in the movement of the gate through the machine, a positng mechanism for said gate, and means for operating said positng mechanism during the pause in the movement of the gate through the machine.

105. In a machine of the character described, in combination, means for moving a gate through the machine, means for arresting the movement of the gate at a predetermined point in the movement of the gate through the machine, supporting members for said gate, a time shaft, means operated by said time shaft for lowering and raising said supporting members, said operating means having a predetermined movement relative to the movement of the gate through the machine.

25 106. In a machine of the character described, in combination, means for moving a gate through the machine, means for arresting the movement of the gate at a predetermined point in the movement of the gate through the machine, supporting members for said gate, a time shaft, a cam on said time shaft, mechanism for lowering and raising said supporting members, said mechanism arranged to be operated by said cam.

35 107. In a machine of the character described, in combination, means for moving a gate through the machine, means for arresting the movement of the gate at a predetermined point in the movement of the gate through the machine, supporting members for said gate, a member extending crosswise of said supporting members, operating connections between said supporting members and said other member, a time shaft, and means operated by said time shaft for lowering and raising said member extending crosswise of the supporting members, and with it said supporting members, and the means for lowering and raising said members having a predetermined movement relative to the movement of the gate through the machine.

45 108. In a machine of the character described, in combination, means for moving a gate through the machine, means for arresting the movement of the gate at a predetermined point in the movement of the gate through the machine, supporting members for said gate, a member extending crosswise of said supporting members, operating connections between said supporting members and said other member, a rock-shaft, connections between said rock-shaft and said member extending crosswise of said supporting

members, and means for operating said rock-shaft from said time shaft to lower and raise said member extending crosswise of the supporting members, and with it said supporting members, the means for operating the rock-shaft having a predetermined movement relative to the movement of the gate through the machine.

5 109. In a machine of the character described, in combination, means for moving a gate through the machine, means for arresting the movement of the gate at a predetermined point in the movement of the gate through the machine, supporting members for said gate, said supporting members extending through the machine in the direction of the movement of the gate therethrough, a member extending crosswise of said supporting members, a series of rock-shafts disposed crosswise of said supporting members, operating connections between one of said rock-shafts and said member extending crosswise of the supporting members, operating connections between the other of said rock-shafts and certain of said supporting members, operating connections between said rock-shafts, a time shaft, means operated by the time shaft for lowering and raising said member extending crosswise of the supporting members, and with it said supporting members, through the connections with said rock-shafts as aforesaid, the means for lowering and raising said members from said time shaft having a predetermined movement relative to the movement of the gate through the machine.

10 110. In a machine of the character described, in combination, means for intermittently moving a gate through the machine, supporting members for said gate, guiding means for said gate, connections between said guiding means and said supporting members, and means for lowering and raising said supporting members, and with them said guiding means, said lowering and raising means having a predetermined movement relative to the movement of the gate through the machine.

15 111. In a machine of the character described, in combination, means for moving a gate through the machine, supporting members for said gate, guiding means for said gate, connections between said guiding means and said supporting members, means for arresting the movement of the gate at a predetermined point in the movement of the gate through the machine, a positng mechanism for said gate, and means for operating said positng mechanism during the pause in the movement of the gate through the machine.

20 112. In a machine of the character described, in combination, means for moving a gate through the machine, said gate having connected thereto uniformly spaced stay

wires and other wires crossing the same, supporting members for said gate, guiding means for said stay wires, means for lowering and raising said supporting members, 5 and means operated by said lowering and raising means for actuating said guiding means during the lowering of said supporting members.

113. In a machine of the character described, in combination, means for moving a gate through the machine, said gate having connected thereto uniformly spaced stay wires and other wires crossing the same, guiding means for said gate, supporting members for said gate, guiding means for said stay wires, means for lowering and raising said supporting members, and connections between said lowering and raising means and said guiding means for the gate 15 and also said guiding means for the stay wires, whereby the guiding means for the gate and said supporting members may be lowered and raised in unison and said guiding means for the stay wires operated during 20 the lowering and raising of the gate.

114. In a machine of the character described, in combination, wire connecting mechanism, means for moving a gate through the machine, said gate having connected thereto uniformly spaced stay wires and other wires crossing the same, supporting members for said gate, means for arresting the movement of the gate when the stay wires and the intersections of said cross wires therewith are brought coincident with said wire connecting mechanism, means for lowering and raising said supporting members, said supporting members being lowered during the pause in the movement of 30 the gate through the machine, means for guiding the stay wires in position crosswise of the wire connecting mechanism, and means for operating said guiding means from said lowering and raising means, 35 whereby said guiding means and said lowering and raising means are operated in unison.

115. In a machine of the character described, in combination, means for moving a gate through the machine, supporting members for said gate, means for lowering and raising said supporting members when the gate has reached a predetermined position in its movement through the machine, 50 guiding means for said gate, said guiding means comprising members adapted to frictionally engage opposite bars of said gate, and connections between said guiding means and said means for lowering and raising 55 said supporting members.

116. In a machine of the character described, in combination, means for moving a gate through the machine, supporting members of said gate, means for lowering 60 and raising said supporting members when

the gate has reached a predetermined position in its movement through the machine, guiding means for said gate, said guiding means comprising members adapted to frictionally engage opposite bars of said gate, 70 one of said guiding members being pivotally connected with an adjustable support, and connections between said guiding means and said means for lowering and raising said supporting members. 75

117. In a machine of the character described, in combination, a row of spaced wire connecting mechanisms, means for moving a gate through the machine, supporting members for said gate, means for lowering and raising said supporting members when the gate has reached a predetermined position in its movement through the machine, guiding means for said gate, 80 said guiding means comprising members adapted to frictionally engage opposite bars of said gate, and located at the opposite ends of the row of said wire connecting mechanisms, and connections between said guiding means and said means for lowering and raising said supporting members. 85

118. In a machine of the character described, in combination, a row of spaced wire connecting mechanisms, means for moving a gate through the machine, said gate having connected thereto uniformly spaced stay wires and other wires crossing the same, 90 supporting members for said gate, means for arresting the movement of the gate when the stay wires and the intersections of said cross wires therewith are brought coincident with said connecting mechanisms, guiding means for said gate, said guiding means comprising members adapted to frictionally engage opposite bars of said gate and 95 located at the opposite ends of the row of said wire connecting mechanisms, means for lowering and raising said supporting members, connections between said guiding means and said means for lowering and raising 100 said supporting members, means for positioning the stay wires crosswise of said wire connecting mechanisms, and connections between said stay positioning means and said means for lowering and raising 105 said supporting members, whereby said positioning means is operated in unison with said lowering and raising means. 110

119. In a machine of the character described, in combination, wire connecting 120 mechanism, a carrier for moving a gate through the machine, said carrier comprising endless chains, means for intermittently operating said endless chains, and means carried by one of said chains adapted to 125 arrest the movement of said operating means, when said gate reaches a predetermined position in the machine.

120. In a machine of the character described, in combination, wire connecting 130

- mechanism, a carrier for moving a gate through the machine, said carrier comprising endless chains, a ratchet wheel and pawl mechanism for operating said chains, means 5 for operating said pawl and ratchet wheel, means for interrupting the engagement of said pawl with said ratchet wheel, and means carried by one of said chains adapted to actuate said pawl interrupting means, 10 whereby the movement of the gate is arrested when it reaches a predetermined position in said machine.
121. In a machine of the character described, in combination, wire connecting 15 mechanism, a carrier for moving a gate through the machine, said carrier comprising endless chains, a shaft for operating said chains, a ratchet wheel carried on said shaft and a pawl adapted to engage said 20 ratchet wheel for intermittently rotating said shaft, means for operating said pawl, a member on said shaft adapted to be moved to a position to interfere with the engagement of said pawl with said ratchet wheel, 25 a lever, connections between said lever and said member, and means carried by one of said chains for operating said lever, said lever being operated at a predetermined movement of the gate through the machine.
122. In a machine of the character described, in combination, wire connecting 30 mechanism, a carrier for moving a gate through the machine, said carrier comprising endless chains, a shaft for operating said chains, a ratchet wheel carried on said shaft and a pawl adapted to engage said 35 ratchet wheel for intermittently rotating said shaft, means for operating said pawl, a member on said shaft adapted to be moved 40 to a position to interfere with the engagement of said pawl with said ratchet wheel, a lever, connections between said lever and said member, means carried by one of said chains for operating said lever and with it 45 said member, said lever being operated at a predetermined movement of the gate through the machine, means for reversing the movement of said shaft and with it said chains, means for interrupting said reversing 50 means when said chains have been moved in a reverse direction to a predetermined position in the machine, and means for returning said member on its shaft to its initial position.
123. In a machine of the character described, in combination, wire connecting 55 mechanism, a carrier for moving a gate through the machine, said carrier comprising endless chains, a shaft for operating said chains, a ratchet wheel carried on said shaft and a pawl adapted to engage said 60 ratchet wheel for intermittently rotating said shaft, means for operating said pawl, a member on said shaft adapted to be moved 65 to a position to interfere with the engage-
- ment of said pawl with said ratchet wheel, a lever, connections between said lever and said member, means carried by one of said chains for operating said lever and with it said member, said lever being operated at a predetermined movement of the gate through the machine, clutch controlled means for reversing the operation of said shaft and with it the chains, means for operating said clutch from said chains when said 70 chains have been moved in a reverse direction to a predetermined position in the machine, and means for returning said member on its shaft to its initial position.
124. In a machine of the character described, in combination, wire connecting 80 mechanism, a carrier for moving a gate through the machine, said carrier comprising endless chains, a shaft for operating said chains, a time shaft, a ratchet wheel carried on said operating shaft, and a pawl adapted to engage said ratchet wheel for intermittently rotating said operating shaft, an eccentric on said time shaft, operating 85 connections between said eccentric and said pawl, a member on said operating shaft adapted to be moved to a position to interfere with the engagement of said pawl with said ratchet wheel, a lever, connections between said lever and said member, means 90 carried by one of said chains for operating said lever, said lever being operated at a predetermined movement of the gate through the machine.
125. In a machine of the character described, in combination, wire connecting 95 mechanism, mechanism for feeding tie-wire stock to said wire connecting mechanism, a drive shaft, a time shaft, driving connections between said drive and time shafts, a 100 carrier for moving a gate through the machine to present the intersections of crossed wires therein to said wire connecting mechanism, means for intermittently operating said carrier from said time shaft, means for 105 arresting the movement of the carrier and with it the gate when the intersections of said wires are brought coincident with said wire connecting mechanism, means for operating said wire connecting mechanism 110 from said time shaft, and means for operating said tie-wire stock feeding mechanism 115 from said time shaft.
126. In a machine of the character described, in combination, wire connecting 120 mechanism, mechanism for feeding tie-wire stock to said wire connecting mechanism, a drive shaft, clutch controlled mechanism for operating said drive shaft, an operator's lever for controlling said clutch controlled mechanism, a time shaft, driving connections between said drive and time shafts, a carrier for moving a gate through the machine to present the intersections of crossed wires therein to said wire connect- 125
- 130

ing mechanism, means for intermittently operating said carrier from said time shaft, means for arresting the movement of the carrier and with it the gate when the intersections of said wires are brought coincident with said wire connecting mechanism, eccentrics on said time shaft, connections between said eccentrics and said wire connecting mechanism for operating said mechanism from said time shaft, a cam on said time shaft, and mechanism operated by said cam adapted in turn to operate said tie-wire stock feeding mechanism, said tie-wire stock feeding mechanism being operated during the interval of time between the operations of said wire connecting mechanisms.

127. In a machine of the character described, in combination, wire connecting mechanism, mechanism for feeding tie-wire stock to said wire connecting mechanism, a drive shaft, a clutch mechanism for controlling the operation of said drive shaft, an operator's foot lever and connections between said lever and said clutch mechanism for controlling the operation of said drive shaft by said clutch mechanism, an additional lever for controlling the release of said clutch mechanism from said drive shaft, a time shaft, driving connections between said drive and time shafts, a carrier for moving a gate through the machine to present the intersections of crossed wires therein to said wire connecting mechanism, means for intermittently operating said carrier from said time shaft, means for arresting the movement of the carrier and with it the gate, when the intersections of said wires are brought coincident with said wire connecting mechanism, means for operating said wire connecting mechanism from said time shaft, and means for operating said tie-wire stock feeding mechanism from said time shaft.

128. In a machine of the character described, in combination, wire connecting mechanism, mechanism for feeding tie-wire stock to said wire connecting mechanism, said tie-wire stock feeding mechanism including an operating shaft, a ratchet toothed wheel on said operating shaft, and a pawl adapted to engage the teeth of said ratchet toothed wheel for intermittently rotating said operating shaft, a drive shaft, a time shaft, driving connections between said drive and time shafts, a cam on said time shaft, connections with said pawl of the tie-wire stock feeding mechanism adapted to be operated by said cam, a carrier for moving a gate through the machine to present the intersections of crossed wires therein to said wire connecting mechanism, means for intermittently operating said carrier from said time shaft, and means for operating the intersections of crossed wires therein to said wire connecting mechanism, means for intermittently operating said carrier from said time shaft, and means for operating

said wire connecting mechanism from said time shaft.

129. In a machine of the character described, in combination, wire connecting mechanism, mechanism for feeding tie-wire stock to said wire connecting mechanism, said tie-wire stock feeding mechanism including an operating shaft, a ratchet toothed wheel on said operating shaft, and a pawl adapted to engage the teeth of said ratchet toothed wheel for intermittently rotating said operating shaft, a drive shaft, a time shaft, driving connections between said drive and time shafts, a cam on said time shaft, connections with said pawl of the tie-wire stock feeding mechanism adapted to be operated by said cam, a carrier for moving a gate through the machine to present the intersections of crossed wires therein to said wire connecting mechanism, a positing mechanism for said gate, when the intersections of said wires are coincident with said wire connecting mechanism, means for intermittently operating said carrier from said time shaft, means for operating said positing mechanism from said time shaft, and means for operating said wire connecting mechanism from said time shaft.

130. In a machine of the character described, in combination, wire connecting mechanism, a carrier for moving a gate through the machine to present the intersections of crossed wires therein to said wire connecting mechanism, an operating shaft for said carrier, a time shaft, means for intermittently operating said operating shaft from said time shaft, mechanism for operating said operating shaft to preliminarily advance said carrier and with it the gate to an operative position in said machine, said last-mentioned mechanism including a ratchet toothed wheel on said operating shaft and an operator's lever and spring detent or pawl adapted to engage said ratchet toothed wheel, mechanism for feeding tie-wire stock to said wire connecting mechanism, means for operating said tie-wire stock feeding mechanism from said time shaft, and means for operating said wire connecting mechanism from said time shaft.

131. In a machine of the character described, wire connecting mechanism, a carrier for moving a gate through the machine to present the intersections of crossed wires therein to said wire connecting mechanism, a drive shaft, a time shaft, driving connections between said drive and time shafts, means for intermittently operating said carrier from said time shaft, means for operating said wire connecting mechanism from said time shaft, mechanism for feeding tie-wire stock to said wire connecting

mechanism, said tie-wire stock feeding mechanism including a ratchet toothed wheel and a pawl adapted to engage the same, a cam wheel on said time shaft, a reciprocating member, a roller on said reciprocating member adapted to be moved by said cam and with it said member, and operating connections between said member and said pawl.

10 132. In a machine of the character described, a series of sets of spaced wire connecting mechanisms, a timing shaft, means for operating said wire connecting mechanisms from said timing shaft, mechanism for feeding tie-wire stock to said wire connecting mechanisms, said last mentioned mechanism including a plurality of pairs of coöperating feeding wheels, an operating shaft for positively actuating said feeding 15 wheels, a ratchet toothed wheel carried on said operating shaft, a pawl adapted to engage said ratchet toothed wheel, a cam on said timing shaft, a reciprocating member, a roller on said reciprocating member adapted 20 to be moved by said cam, operating connections between said member and said pawl, and wire guiding tubes between said feeding wheels and said wire connecting mechanisms for the passage of said tie-wire 25 stock.

133. In a machine of the character described, in combination, a series of sets of spaced wire connecting mechanisms, a timing shaft, means for operating said wire connecting mechanisms from said timing shaft, mechanism for feeding tie-wire stock to each of said wire connecting mechanisms, said last mentioned mechanism including an operating shaft, a plurality of feeding 30 wheels on said shaft, a shaft driven from said operating shaft, a plurality of feeding wheels carried on said last mentioned shaft and adapted to coöperate with the feeding wheels on said operating shaft for feeding 35 said tie-wire stock, a means for yieldingly holding each of said last mentioned feeding wheels in coöperative relation with said feeding wheels on the operating shaft, and means for intermittently operating said operating shaft from said timing shaft.

134. In a machine of the character described, in combination, a series of sets of spaced wire connecting mechanisms, a timing shaft, means for operating said wire connecting mechanisms from said timing shaft, mechanism for feeding tie-wire stock to each of said wire connecting mechanisms, said last mentioned mechanism including an operating shaft, a plurality of feeding 50 wheels on said shaft, a shaft driven from said operating shaft and having an elongated driving gear thereon, a plurality of feeding wheels on said last mentioned shaft adapted to coöperate with the feed-

ing wheels on said operating shaft, each of said wheels having an internal gear adapted to mesh with said elongated driving gear, a means for yieldingly holding each of said last mentioned feeding wheels in coöperative relation with said feeding wheels on the operating shaft, and means for intermittently operating said operating shaft from said timing shaft.

135. In a machine of the character described, in combination, a series of sets of spaced wire connecting mechanisms, a timing shaft, means for operating said wire connecting mechanisms from said timing shaft, mechanism for feeding tie-wire stock to each of said wire connecting mechanisms, said last mentioned mechanism including an operating shaft, a plurality of feeding wheels on said shaft, a shaft driven from said operating shaft, a plurality of feeding wheels carried on said last mentioned shaft and adapted to coöperate with the feeding wheels on said operating shaft, each of said wheels geared directly to said shaft, a friction bearing block for each of said last mentioned wheels, and adjusting means for said bearing blocks, whereby a coöperative relation may be brought about between said feeding wheels for feeding said tie-wire stock, the release of said adjusting means releasing said feeding wheels and preventing the feeding of said tie-wire stock, and means for intermittently operating said operating shaft and said timing shaft.

136. In a machine of the character described, in combination, a series of sets of spaced wire connecting mechanisms, a timing shaft, means for operating said wire connecting mechanisms from said timing shaft, mechanism for feeding tie-wire stock to each of said wire connecting mechanisms, said last mentioned mechanism including an operating shaft, a plurality of feeding wheels on said shaft, a second shaft geared to and driven from said operating shaft, and having a driving gear thereon, a plurality of feeding wheels on said last mentioned shaft, each of said wheels having an internal gear adapted to mesh with and be driven by said driving gear, said feeding wheels on said operating shaft and the shaft driven therefrom being arranged in pairs, each pair adapted to feed a single tie-wire stock to a set of said wire connecting mechanisms, and means co-acting with each of said internally geared feeding wheels for regulating their operative relation with the feeding wheels on said operating shaft, and means for intermittently operating said operating shaft from said timing shaft.

137. In a machine of the character described, in combination, a plurality of hollow cutting and bending blocks, said blocks having diagonally arranged slotted open-

ings therein, a vertically movable plate to which said bending blocks are secured, a driving member operatively carried in each of said bending blocks, a vertically movable plate to which all of said driving members are connected, an anvil for each bending block normally disposed in the slotted openings therein, pivoted supports for each of said anvils, a stationary die-member located below and spaced from each of said bending blocks, a timing shaft, means on said timing shaft for raising and lowering the plate to which the cutting and bending blocks are secured for moving the same toward and from said die-members, other means on said timing shaft for raising and lowering said driving members in said bending blocks, and means for feeding tie-wire stock to each of said cutting and bending blocks

138. In a machine of the character described, in combination, a plurality of hollow cutting and bending blocks, said blocks having diagonally arranged slotted openings therein, a vertically movable plate to which said bending blocks are secured, a driving member operatively carried in each of said bending blocks, a vertically movable plate to which all of said driving members are connected, an anvil for each bending block normally disposed in the slotted openings therein, and yieldingly held in such position, pivoted supports for each of said anvils, a stationary die-member located below and spaced from each of said bending blocks, a timing shaft, a plurality of eccentrics on said timing shaft, connections between said eccentrics and said plate to which said cutting and bending blocks are secured for raising and lowering said blocks in unison, other eccentrics on said timing shaft, connections between said eccentrics and said plate to which are secured said driving members for raising and lowering said driving members in said bending blocks in unison, said eccentrics being so arranged on said timing shaft and adjusted relatively to each other, whereby the cutting and bending blocks in their downward movement will precede the

movement of said driving members, and means for feeding tie-wire stock to each of said cutting and bending blocks.

139. In a machine of the character described, in combination, a plurality of vertically movable hollow cutting and bending blocks, said blocks having diagonally arranged slotted openings therein, an anvil for each bending block normally disposed in the slotted openings therein, means for yieldingly holding the anvils in such position, vertically movable driving members, one for each bending block and movable therein, means for raising and lowering said bending blocks, means for raising and lowering said driving members, a stationary die-member located below and spaced beneath said bending blocks, means for feeding tie-wire stock across the lower ends of said bending blocks and across the ends of said anvils, wire guiding means connected to and movable with said bending blocks, and wire guiding means associated with each of said die-members, said last mentioned wire guiding means comprising hinged plates and means for yieldingly holding the same in operative position.

140. In a machine of the character described, in combination, a suitable framework, wire connecting mechanism, a carrier for moving a gate through the machine to present the intersections of crossed wires therein to said wire connecting mechanism, guiding means for said gate, said guiding means including a pivotally supported member adapted to engage one of the bars of said gate at one side of said wire connecting mechanism, and coöperating friction gripping members having a yielding relation and adapted to engage a bar of the gate on the opposite side of said wire connecting mechanism, means for raising and lowering said guiding members in unison and with them the gate, and bearing means for said friction gripping members adapted to move on said framework as the same are raised and lowered.

WILLIAM H. SOMMER.
